AUTOMATIC LOOM

Henry Downer Johnson, Jr., and Woodruff T. Sullivan, Norwich, Conn., assignors to J. B. Martin Company, Norwich, Conn., a corporation of Delaware

Application November 15, 1933, Serial No. 698,044

46 Claims. (Cl. 139—224)

The present invention relates to looms and it particularly relates to automatic shuttle changing mechanism in which the shuttles when exhausted are removed from the loom and are replaced by refilled shuttles containing a new supply of the filler.

Although not restricted thereto, the present invention will be illustratively described in application to an automatic shuttle box unit changing mechanism for double shuttle looms which are designed for the weaving of pile fabrics.

In the usual type of two shuttle or double shuttle loom the interruption in operation occasioned by stoppage of the loom to replace an exhausted shuttle with a fully stocked shuttle not only causes a loss in time and a decrease in the amount of material produced but in addition, causes a change in the tension of the warp, resulting in an imperfect fabric.

20 In the case of double shuttle looms for weaving pile fabrics, the curtailment in production due to these periodical shutdowns is of considerable consequence and results in a substantial increase in manufacturing costs and further in

25 a lower grade fabric.

An object of the present invention is to provide an automatic shuttle changing mechanism particularly adapted for plural-shuttle looms, in which the shuttles will be automatically changed and replaced by refilled shuttles, when exhausted, without requiring the weaver's attention, with a substantial reduction in manufacturing costs and with the production of a more perfect fabric, and which mechanism may be attached to looms now in operation without expensive or substantial modification or alteration thereof.

In accomplishing the above objects, particularly in the case of double shuttle looms, it was found desirable in one embodiment to replenish both of the shuttles simultaneously when either one of the shuttles became exhausted, so that the shuttles being utilized would carry about the same amount of filler thread throughout operation and will become exhausted together.

40 This is accomplished in the specific embodiment shown and described by receiving the shuttles at one side of the loom in a replaceable shuttle box unit, which replaceable operating box units may be conveniently moved out of position when exhausted to be replaced by another replaceable reserve box unit conveniently inserted to take its place.

45 It was found convenient in one embodiment to provide a frame which moved with the lay to receive the operating shuttle box unit and

the reserve shuttle box unit, so that when the operating box unit was moved from the operating position, the reserve box unit would move down in said frame into said operating position, preferably during the interval between when the exhausted shuttles were received in their operating box unit and when the pickers were actuated to throw the new shuttles out of the new operating box unit.

50 In the embodiments shown and described, to remove the exhausted shuttle box unit and to permit the reserve shuttle box unit to move into position, it was found convenient to employ a carrier or elevator structure which may be lowered and elevated by a cam synchronized with the operating mechanism of the loom.

This cam was actuated in such a way as to move or permit movement of the elevator to release the exhausted shuttle box unit, at the same time permitting the reserve box unit to fall into position, this operation being accomplished before the next operation of the pickers. Preferably, about the same time the downward movement of the carrier or elevator causes a new reserve box unit to be received into the frame from a magazine carried on the loom structure, this transfer operation preferably taking place at one of the extreme ends of travel of the lay.

55 In constructing the apparatus as above described, it is desirable to provide means for preventing damage if the exchange does not take place properly and this is desirably accomplished by connecting a safety device to the dagger mechanism of the loom so as to stop the loom if the exchange were not properly accomplished.

It has also been found desirable to provide means for severing the filler threads from the exhausted shuttles, preferably actuated in synchronism with the movement of the lay and the transferring operation.

40 The above and other objects will appear more clearly from the following detailed description, when taken in connection with the accompanying drawings, which illustrate several preferred embodiments of the inventive idea.

45 In the drawings:

Figure 1 is a diagrammatic front view of a loom illustrating the relative position and connection of the various elements, the main actuating cam being turned 90° out of position to more clearly illustrate its operation.

Figure 1a is a diagrammatic side view of a loom to which the box unit changing mechanism of the present invention may be most conveniently applied.

Figures 2, 3, 4 and 5 respectively illustrate the successive positions of the operating and reserve box units containing the shuttles during the shuttle changing operation.

5 Figures 2a, 3a, 4a, and 5a illustrate the corresponding positions of the main actuating cam when the box units are in the position shown in Figures 3, 4 and 5 respectively.

Figures 6 to 9a illustrate the shuttles in position in fixed double shuttle box on the other side of the loom, the right side in the embodiment shown, together with the associated mechanism and connections which initiate operation of the shuttle box unit changing arrangement at the left side of the loom; Figure 6 being a top view of the upper shuttle in position in the fixed top box; Figure 7 being a side sectional view upon an enlarged scale on the line 7-7 of Figure 6; Figure 8 being fragmentary enlarged top view of one end of the shuttle in partial section showing the quill; Figure 9 being a fragmentary sectional view of the shuttle illustrating the contact arrangement taken upon the line 9-9 of Figure 8; and Figure 9a is an enlarged fragmentary side sectional view upon the line 9a-9a of Figure 6 illustrating the electrical connections in the fixed double shuttle box structure.

Figures 10, 11 and 12 illustrate the main actuating cam together with its associated cam lever and latches, Figure 10 being a side view upon the line 10-10 of Figure 11 and Figure 11 being a top view in the direction indicated by 11 of Figure 10; Figure 12 being a side view in the direction indicated by 12 in Figure 11.

35 Figures 13 and 14 illustrate the shuttle box unit changing mechanism at the left side of the lay; Figure 13 being a front view in the direction indicated by the numeral 13 in Figure 14 and Figure 14 being a side view in the direction indicated by the numeral 14 in Figure 13, Figure 13 showing the lay in extreme forward position, while Figure 14 shows the extreme rear position.

Figure 15 is a side view upon an enlarged scale of the upper portion of the changing mechanism taken in the direction indicated by the arrow 15 in Figure 13.

Figure 16 is a side sectional view upon an enlarged scale of the upper portion of the changing mechanism taken along the line 16-16 in Figure 13.

50 Figure 16a is a side sectional view upon an enlarged scale of the upper portion of the changing mechanism taken along line 16a-16a of Figure 13.

55 Figures 16b and 16c show the device for cutting the filler or weft of the exhausted shuttles when they are replaced by refilled shuttles, Figure 16b being a side view taken in the direction 16b of Figure 16c and Figure 16c being a front view taken in the direction 16c of Figures 16a and 16b.

Figure 17 is an enlarged showing of the left hand portion of the mechanism shown in Figure 13 and taken in the direction indicated by the 65 numeral 17 in Figure 15.

Figure 18 is a section upon an enlarged scale upon the line 18-18 of Figures 13 and 17 showing the gripper finger mechanism.

Figures 19, 20, 21 and 22 are top sectional views 70 upon the lines 19-19, 20-20, 21-21 and 22-22 of Figs. 13 and 14, Figs. 19 and 20 being sections on the magazine structure and Figures 21 and 22 being sections on the upper portion of the lay end or elevator frame structure, Figure 20 being 75 broken and of decreased width.

Figure 23 is an enlarged side sectional view upon the line 23-23 of Figure 22 showing the pickers which actuate the shuttles, the shuttles not being in position.

Figure 24 is a detail section on an enlarged 5 scale upon the line 24-24 of Figures 17 and 23 showing the releasing mechanism for the box unit holding pins.

Figure 25 is a top sectional view upon the line 25-25 of Figures 13, 15, 16 and 17 showing the exhausted shuttle box unit ejecting mechanism, Figure 25 also showing the position of the lay end or elevator frame in dotted lines when the box unit containing the exhausted shuttles have been removed therefrom and the lay has started 15 to move rearwardly.

Figure 26 is an enlarged detail front elevational view of the picker stick releasing mechanism, taken in the direction as indicated by the numeral 26 on Figure 14 at the lower left corner of the elevator frame structure. 20

Figures 27, 28, 29, 30 and 31 show the replaceable shuttle box unit construction which receives the shuttles and which is adapted to supply the refilled shuttles and remove the exhausted shuttles, Figure 27 being a top plan view in the direction indicated by the numeral 27 on Figure 28, Figure 28 being a front view in the direction indicated by the numeral 28 in Figure 27, Figure 29 being a rear view in the direction indicated by 30 the numeral 29 in Figure 27, Figure 30 being a side elevational view in the direction indicated by the numeral 30 in Figure 28, and Figure 31 being a side sectional view upon the line 31-31 of Figure 27. 35

Figures 32, 33 and 34 illustrate the safety device, Figure 32 being an enlarged showing of the mechanism indicated by the numeral 32 in Figure 14, Figure 33 being a front view in the direction indicated by the numeral 33 on Figure 32 40 and Figure 34 being an enlarged sectional view upon the line 34 of Figure 13 illustrating the dagger rod actuating mechanism.

Figures 35 and 36 show the exhausted shuttle box unit receiving arrangement, Figure 35 being a front view as shown in direction indicated by the numeral 35 on Figure 14, and Figure 36 being a side sectional view upon the lines 36-36 of Figure 35.

Figure 37 is a detail of the elevator lowering 50 rods partially in section, taken in the direction indicated by the numeral 37 on Figure 14.

Figure 38 is a graph illustrating the respective movements of the exhausted shuttle box unit, the lay and the elevator during the shuttle box 55 unit changing operation.

In Figures 1 and 1a is shown diagrammatically in front and side views one form of a loom construction of the double shuttle type adapted for weaving pile fabrics. 60

In Figure 1a the warp beam 50 carries the upper and lower warps 51 and 52 to form the ground of the pile fabric. The warp beam 50 is held under tension by a weight arrangement or other means (not shown). The warp is fed 65 across the rolls 53, 54, and 55 to the warp heddles 56 and 57, which respectively control the upper and lower ground or base warp threads of the fabrics 68 and 69, said heddles being held on suitable harness frames 56', 56'', 57' and 57''. 70

The pile warp 58 is carried on the warp beam 59 and passes over the pile rods 60 to the controlling heddles 61 which are operated with the heddles 56 and 57 by harness frames 61' and 61''. 75

The lay 62 (see Figures 1 and 1a) is carried by

the lay swords 62a on the rocker shaft 63 and carries the shuttle boxes, the bed 62b and the reed 64. The shuttles are adapted to traverse the warp or shed, as the positions indicated at 65, with the result that a double fabric as indicated at 66 is formed, which is cut by the reciprocating knife 67 into the top piece 68 and the bottom piece 69 (see also Figures 13 and 16a).

As is apparent the weaving or formation of both an upper and lower base fabric or ground for the pile necessitates the movement of two shuttles across the shed or warp for each pick and it has been found most satisfactory to throw both of the shuttles over simultaneously to the left of the loom and then back again to the right during the weaving operation, the heddles changing the sheds or relative positions of the warp threads during the intervals between the passage of the shuttles.

20 In Figures 1 and 1a the lay 62 is diagrammatically illustrated as turning on the rocker shaft 63, the bed of the lay 62 forming the race for the lower shuttle 72 while the shed or warp forms a runway for the upper shuttle 72. These 25 runways or paths for the shuttles are indicated at 65.

The apparatus as described up to this point is the conventional double shuttle loom construction, which loom construction is particularly adapted for the weaving of pile fabrics and the present invention is particularly directed and its novel features consist primarily in the manner of replacing the shuttles 72 when their supply of filler or weft has been exhausted.

35 It has been found particularly desirable in changing the shuttles of double shuttle looms of the character described to replace both shuttles simultaneously and automatically after a transfer has been indicated, between the time that 40 the exhausted shuttles are received in their operating box unit, and the time of the picker stick throw on the transfer side of the loom so that two refilled shuttles will be simultaneously moved into operating position to be thrown across the 45 sheds by the next throw of the picker stick.

In accomplishing this it has been found most satisfactory to receive both shuttles in a replaceable shuttle box unit which is positioned at one side of the loom, illustratively on the left side, 50 as shown in Fig. 1 at 75.

As shown in Figure 1 the shuttles 72 are received in the fixed double shuttle box structure 73 at the right of the loom, from which box structure they are thrown to the left by the picker stick 74 into the replaceable operating box unit 75. From the box unit 75, the shuttles may be thrown to the right again through the sheds by the picker stick 76, the left hand picker stick 76 and the right picker stick 74 being alternately operated to throw the shuttles back and forth across the lay 62 (see also Figure 13).

55 In Fig. 1, the replaceable operating shuttle box unit 75, to be more fully described in connection with Figs. 27 to 31, is received upon an elevator mechanism 77 having the central lifting rod 78 and an elevator frame structure 79 (to be more fully described in connection with Figs. 13 to 17).

70 The elevator frame 79, which moves with the lay 62, receives the reserve box unit 75'; as well as the operating box unit 75. The stationary magazine 83 positioned above the elevator frame 79 is provided with a series of additional double shuttle box units 75², 75³ and 75⁴, each containing refilled shuttles 72², 72³ and 72⁴, respectively.

When one of the operating shuttles 72 (see Fig. 1) becomes exhausted, i. e. its filling or weft is substantially depleted, a trigger (to be more fully described in connection with Figs. 8 and 9) contained in such shuttle 72 will be released and will close the contacts 80 in the fixed shuttle box 73, which will complete a circuit through the electrical circuit 81 supplied with energy from the electrical source 82 which may take the form of batteries or an A. C. or a D. C. power 10 supply.

When the electrical circuit 81 (see Fig. 1) is closed through the contacts 80, operation of the shuttle box unit changing mechanism will be initiated.

Although the shuttle box unit changing operation may take place in any desired number of picks or may be widely varied to take place in any sequence relative to the operation of the loom, it has been found most satisfactory to regulate this changing operation so that it will be completed during four picking operations.

For example, when the circuit 81 is closed through the contacts 80 due to the depletion of the weft or filling threads in the fixed double shuttle box 73, the following sequence of operations will take place. The two shuttles 72 which are about to become exhausted are thrown back to the other side of the loom from the fixed box 73 by the operation of the picker stick 74, at the other side of the loom, they will be received in the replaceable box unit 75, and then immediately the box unit 75 will be lowered on the elevator 77, removing the two depleted shuttles. At the same time the reserve box unit 75 is permitted to fall into operating position, so that the two new shuttles 72' will be thrown back at the next operation of the picker stick 76. The filler contained in the two new shuttles 72' is tied together so that when the shuttles enter the shed on the first pick the new incoming filler is stopped by the edge of the cloth.

After the throw of the shuttles 72 (about to be replaced) from the fixed double shuttle box 73 to the replaceable box unit 75 has been completed, the lay 62 is moved forwardly together with the reed 64, which reed will beat or move the pick or filler thread, left after passage of the flying shuttles, into proper position at the fell of the fabric.

50 When the lay 62, carrying the elevator frame or lay end 79, is moved to its extreme forward position, the lowermost box unit 75² in the stationary magazine 83 will be engaged by the elevator frame 79 so that when it moves rearwardly it will carry with it this lowermost box unit 75² of the magazine, which will become the new reserve box while the original reserve box unit 75¹ will become the new operating box unit.

The exhausted operating box unit 75 will be lowered to the bottom of the frame 79 from which it will be ejected when the lay 62 has again moved to its most forward position. Then the elevator 77 will be raised to its normal position.

This shuttle box unit changing operation is primarily caused, in the embodiment shown, by movement of the elevator 77 in the frame 79, which elevator 77 is caused and/or permitted to move by the main actuating cam 84 which is shown turned 90° out of position in Fig. 1, for the purpose of better illustration, (which cam will be more fully described in connection with Figs. 10 to 12).

The cam 84 is driven by the actuating mechanism of the loom and is caused to turn one revo- 75

lution for four picks and four complete reciprocations of the lay 62.

When the box unit changing operation is taking place and the cam 84 is actuating the elevator 11 the successive positions of the cam 84 and of the elevator are shown respectively in Figs. 2 and 2a, Figs. 3 and 3a, Figs. 4 and 4a and Figs. 5 and 5a for each of the four picking operations until the completion of the shuttle box unit changing operation.

When the circuit is closed through the contacts 80 on Fig. 1 due to the depletion of the shuttles 12, the contact element 85 which turns with the cam 84 will also complete the circuit through the contacts 86 and cause energization of the solenoid 87. The solenoid 87 is supported on and reciprocates with the lay rocker shaft 63.

The arm 89 pivotally carrying the latch 90 at 91 also reciprocates with the lay 62. The left end 20 of the latch 90 as shown in Fig. 1, which is the forward end when the latch 90 is in proper position on the loom, will be turned counterclockwise by the solenoid 87 so that the rear or right end of such latch at 92 will be moved upwardly and will 25 contact with the tooth 93 on the lever 94.

Since the latch 90 moves with the lay the contact of the members 92 and 93 will move the lever 94. This lever 94 will actuate the bell crank 30 lever 95 and disengage the latches 96 and 97. The latch 96 is on the cam follower arm 98 provided with the follower 88 which rides upon the depressed portion of the cam 84 during the shuttle box unit changing operation.

As shown in Fig. 1, the cam follower arm 98 is 35 provided with an extension 100 to the end of which is connected the chain 101 passing over the roller 102. The chain 101 is connected to the motion multiplying lever 103 which is pivoted at 104. The other end of the motion multiplying 40 lever 103 is provided with a chain connection 105 which chain connection passes over the rollers 106 and 107 and is connected to the central control rod 18 of the elevator 11 permitting the elevator 45 to lower.

The elevator 11 upon its descent will actuate a 50 releasing mechanism to permit the operating box unit 15 containing the exhausted shuttles 12 to be carried by the elevator 11 out of operating position. At the same time the reserve box unit 15' will be permitted to fall into the position of the operating box unit.

The movement of the elevator 11 will also 55 actuate a device, whereby the elevator frame 19 will receive an extra shuttle box unit 15', as a new 60 reserve box unit, from the stationary magazine 83, when the lay 62 is in the extreme forward position.

During the intervals between the shuttle box 65 unit changing operation the latch 90 will remain elevated from the solenoid due to its greater weight being on the other side of the pivot 91, and the tooth 92 will be lowered sufficiently below the tooth 93, so that no engagement therebetween will take place during the forward and rearward 70 movements of the lay. At the same time the latches 96-97 will remain engaged and the cam roller 88 will not follow the depressed portion of the cam 84. Accordingly the elevator 11 will be held in its normal position as indicated on Fig. 1.

It is only when the circuit is closed through the contacts 80 energizing the solenoid 87 and releasing the latches 96 and 97, that the roller 88 75 may follow the depressed part of the cam 84, low-

ering the elevator 11, whereby the box unit changing operation will be caused to take place.

As previously stated, although the shuttle box unit changing operation may be caused to take place in any desired number of picks it has been found satisfactory in one embodiment to cause it to take place in four picks and the cam 84 as shown is a four pick cam making one complete revolution for four picks or throws of the shuttles 12, or complete reciprocations of the lay 62.

Since the cam 84 is a four pick cam it is necessary that the cam 84 be permitted to perform the operation by energization of the solenoid 87 only when the cam follower 88 (see Fig. 2a) is in the position indicated at the quadrant 15 108 on the face of the cam and not in the position indicated at the quadrant 109. For this reason, the extra circuit breaker arrangement 85-86 is provided which assures that the circuit will be closed only when the follower 88 is 20 in the quadrant 108. If the follower is in the opposite quadrant at 109 where it would be elevated from the depressed surface of the cam 84 during normal operation, when the contact is closed at 80, due to the depletion of the filler 25 in a shuttle 12, the circuit will be open at the contacts 86 since the element 85 will be turned upwardly.

It will then be necessary for the shuttles 12 to return to the left hand replaceable operating 30 box unit and then again to the right hand box 13, again completing the circuit 81, while the cam at the same time rotates through 180°. At this point the follower 88 will be in the quadrant 108, the circuit will be closed through the 35 contacts 86 and the solenoid will be energized, permitting the follower 88 to follow the cam. This operation will be more specifically described in connection with Fig. 10.

Referring to Figs. 2 to 5 and Figs. 2a to 5a, 40 as well as Fig. 1 the lay 62 is shown in Figs. 2, 3, 4 and 5 as having completed its forward reciprocation from its rearmost position 62 after each throw of the shuttles 12, the lay being driven through the crank connector 110 and the crank 45 111, as diagrammatically illustrated. As indicated by the arrows 112 the crank is moved clockwise and the shuttles 12 traverse the shed during the period the crank 111 moves over the arc 113, the shuttles 12 dwelling in either the right 50 hand fixed double shuttle box 13 or left hand replaceable box unit 15 during the supplementary arc 114.

In Figs. 2 and 2a, assuming that the cam 84 is in proper position while the lay 62 is moving 55 backwardly and then again forwardly from its previous foremost position to the position of Fig. 2, the follower 88 will have moved over the quadrant 108 as indicated in Fig. 2a and the shuttles 60 will have moved from the replaceable box unit 15 to the fixed double shuttle box 13. When the shuttles 12 enter the fixed right hand double 65 shuttle box 13, either one or both the shuttles having been exhausted, the contacts 86 will be closed, at the same time as the contacts 86 are 70 also closed by the contact element 85 on the clockwise rotating cam 84, during the arc 115 of Fig. 2a. This will release the cam follower lever 88 of Fig. 1, so that when the cam follower roller 88 reaches the position 116 on the cam it will 75 follow the contour of the cam from 116 to 117 and will not be held above the surface of the cam by the interlocking latches 96 and 97 which would cause it to follow the dotted circle 118 between the points 116 and 117.

In Figs. 3 and 3a, while the follower 88 is moving through the quadrant 119, on the cam 84, the exhausted shuttles will first be thrown back to the replaceable shuttle box unit 75. After they have been received in this box unit, the cam follower 88 will pass the point 116, whereupon the roller 88 will follow the depressed contour of the cam between the points 116 and 117.

As the roller follows the depressed portion of the cam from the point 116 in a clockwise direction, the elevator 77 will descend, causing release of the pins 355 which hold the exhausted box unit 75. As soon as this occurs, the exhausted box unit 75 will drop to the elevator 77 and will be carried downwardly out of operating position upon continuous descent of said elevator.

At the same time the reserve box unit 75' will slide down into operating position, taking the place of the exhausted box unit 75, the shuttles 72' of the new box unit 75' now being the operating shuttles, as indicated in Figure 3.

At the same time as the lay is in the position of Fig. 3 the lowermost box unit 75² of the magazine will be received in the elevator structure and will be carried rearwardly with the lay during the movement of the lay from the position of Fig. 3.

The replacement of the exhausted operating box unit 75 by the reserve box unit 75' and the reception of a new reserve box unit will all take place within the arc 122 indicated upon Fig. 3a. During the quadrant 121 of Fig. 4a, while the lay is moving from the position of Fig. 3 to the position of Fig. 4, the new shuttles 72' will be thrown across the shed to the opposite fixed double shuttle box unit 73.

During the reciprocation of the lay from the position of Fig. 3 to the position of Fig. 4 the follower 88 will be moved entirely through the quadrant 121, lowering the exhausted box unit 75 to its lowermost position, as indicated in Fig. 4.

At this point the ejector means 600, (more fully described in connection with Fig. 25) will grip the exhausted box unit 75 during the rearward movement of the lay 62 from the position of Fig. 4 to that of Fig. 5, while the roller 88 is moving over the initial part of the quadrant 124 the box unit 75 will be removed.

After such removal, the follower 88 will continue to move over the quadrant 124 and the elevator 77 will be raised again to its normal position to a position below the new box unit 75' where it will remain until the filler of one or other of the shuttles 72' has become exhausted. At the same time the latches 96 and 97 will be connected and the roller 88 will be prevented from following the cam 84.

The mechanism which has been now briefly described in connection with the diagrammatic showings of Figs. 1 to 5a involves many novel features and combinations which will now be more specifically described in connection with detailed showings thereof.

In Figs. 6 to 9a are shown the details of fixed double shuttle box 73, together with the contact connections of the shuttles 72. In Figs. 6 and 7 the shuttles 72 are shown in the fixed double shuttle box 73, in which they have been stopped by the spurs 150 thereof fitting into the pickers 151 which are actuated by the picker stick 74 of Fig. 1.

As shown in Fig. 7 the shuttles 72 are received in the recesses 152 in the fixed double shuttle box 73. When received in such recesses they press the swell members 153 to the rear against

the springs 149. The swell contact members 154 of the levers 155 will be thereby moved outwardly rotating the dagger shafts 157 and 142. The dagger 156 on the shaft 157 cooperates with a bumper 159 when the shuttles 72 are not in either of their boxes 73 and 75 after the throw to stop the loom.

Within each shuttle is a quill or bobbin 160 carrying the filler or weft 161 (see Figs. 8 and 9). The larger end of the quill 162 fits over a spindle 163 which has a pivotal connection at 164 to the shuttle body. When the quill is to be removed and/or a new refilled quill is to be inserted, the spindle 163 is turned downwardly from its position in Fig. 9 on the pivot 164 15 against the snap spring 140. When the spindle is moved back it will be stopped against the stop pin 141.

The pivot member 164 is of metal and is connected to the contact 165 on the side of the shuttle (see Fig. 9a). Fitting in a slot 166 in the spindle 163 is the trigger 167 which is held within the slot by the filler 161. When the filler 161 is exhausted the trigger 167 will be released thereby and caused to spring outwardly by the leaf spring 168 to contact with the pin 169, which pin 169 is connected to the other contact 170 along the side of the shuttle (see Fig. 9a).

As shown in Fig. 9a, in the side of the fixed double shuttle box 73 are the contact members 80 which are pressed against the contact plates 165 and 170 by the springs 171. The springs 171 fit upon the rods 172 of the contacts 80, and are enclosed in the sleeves 173. The electrical conduits 81 lead from said sleeves 173.

When the filling 161 is exhausted and the trigger 167 has been released to contact with the pin 169, the circuit will be closed from the contact 165 to the contact 170 through the spindle 163, the pivot rod 164 thereof, the trigger 167 and the pin 169.

If the trigger 167 completes the circuit when the roller 88 is in the quadrant 124 of Fig. 5a, there will still be sufficient filler 161 on the quill at 161a (see Fig. 9) beyond the trigger 167 to permit the shuttles 72 to be thrown across the shed three more times as the roller 88 moves through the quadrants 121, 124, 119 and 108 of Figs. 2a to 5a.

Figs. 10 to 12 show the main actuating cam 84, the plane of which is turned 90° from the position which is diagrammatically shown in Fig. 1. In those figures the lay rocker shaft 63 carries the collar 185 which is fixed to it by the set screw 186, said ring 185 carrying the electromagnet stand 205. The electromagnet stand 205 carries the solenoid 87 which is energized by the electrical circuit 81 leading from the contacts 80 which are closed upon depletion of the shuttles.

The collar 185 also carries the upwardly extending arm 89 to the upper clevised portion of which is pivotally connected the latch 90 at 91. The latch 90 is provided with a forward armature end 187 which is drawn against the core 188 of the electromagnet 87 upon energization 65 thereof. The movement of the forward end 187 is stopped by the yoke member 189, fixed to the electromagnet carrier 205, to prevent it from being elevated too far above the core 188.

The rear end 190 of the latch 90 is substantially heavier than the forward end 187 so that when the forward end 187 is not attracted by the electromagnet 87 the heavy end 190 of the latch 90 will descend, raising the forward end 187 until it is stopped by the yoke 189.

The rear end of the latch 90 is provided with a latch contact member 92 which, when the electromagnet 87 is not energized, is held by the weight of the portion 190 below the cooperating latch 93 on the actuating arm 94.

The actuating arm 94 is guided between the pins 191 on the upper portion of the clevis of the arm 89. At its rear end, the arm 94 is pivotally connected at 192' to the upwardly projecting ear 201 of the elongated hub 225 of the latch member 95 having the latching tooth 97.

The hub 225 of the latch member 95 is pivotally mounted on the shaft 192, which is supported on the frame of the loom fragmentarily illustrated by the longitudinal member 193 and the front and rear cross beam members 194 and 195. These members 194 and 195 are respectively connected as indicated by the flanges 196 and 197, and the bolts 198 and 200 to the longitudinal member 193.

The latch 97 cooperates with the latch 96 on the cam follower lever 98 and the latch teeth 96 and 97 are held in contact by the spring 202 connected between the forwardly projecting ear 203 of the latch 95 and the ear 204 which is rigid in respect to the frame of the loom 193—194—195.

The cam follower lever 98 is pivotally mounted on the rod 206 supported upon the stand 224 fixed to the frame member 193 of the loom. The arm 98 is provided at its rearmost end with a curved portion 208 carrying the follower roller 99 which rides over the surface of the cam 84.

The cam 84 is mounted on the shaft 209 which is in turn mounted on the longitudinal member 193 of the loom frame by the bracket 214. The cam 84 is driven through the pinion 210 and the gear 211 from the actuating mechanism of the loom, so that it will make one complete revolution for four picks or four complete revolutions of the crank 111 of Figs. 2 to 5.

Projecting upwardly from the loom frame member 195 is the arm 212 to the end of which is connected the spring contacts 86, which are two in number, as indicated by the dotted lines in Fig. 11. When the cam is in proper position (as indicated in Fig. 2a) the contacts will be circuited across the metallic face 213 of said contact member 85. The contact member 85 turns, 50 as does the cam 84, on the shaft 209.

The driving gear 211 is bolted to the cam 84 at 215 (see Fig. 10) so as to form a unit therewith.

The forward end 198 of the cam follower lever 55 is provided with an adjustable clevis member 217 fixed in position by the locking nut 218 on the clevis to which is connected the chain 191 by the pin 220.

The clevis 217 (see Fig. 10) is provided with an ear 221 to which is attached the spring 222. The spring connection 222 actuates the lever 223 when the forward end of the cam lever 198 is in lowered position. This happens when the roller 88 is permitted to follow the depressed portion of the cam upon disengagement of the latches 86 and 87. When the lever 223 is drawn downwardly by downward movement of the arm 190 of the cam lever, a switch is closed in the box 226, which causes an indication to the operator of the loom. He will thus be informed that the roller is following the depressed portion of the cam 84 and a transfer is in operation, changing the shuttle box units 18' and 18".

The link chain 191 (see Figs. 11 and 12) extends downwardly from the clevis 217 and passes

over the roller guide 102 and then extends to the end of the short arm 228 of the multiplying lever 103. The hub 230 of the lever 103 is rotatable upon the shaft 104 supported by the bracket 232. The bracket 232 is in turn supported upon the 5 rocker shaft 63 by the clamp 233. The lower end of the long arm 234 of the multiplying lever 103 is connected to the chain 105 which leads to the elevator 11 of Fig. 1.

Each arm 228 and 234 of the multiplying lever 10 103 is provided with a rounded portion 236, which is tapped to receive the chain attachment clevis 231. The chain attachment clevis is locked in position by the lock nuts 238, see particularly Fig. 12.

In Figs. 13 and 14 are shown the stationary magazine structure 83 and the elevator frame structure 78. The oscillating lay 62 is in extreme rear position in Fig. 14 and extreme forward position in Fig. 13, reciprocating on the rocker shaft 20 63. The lay 62 carries the elevator frame 78. The elevator frame 78 carries the elevator 11, the operating shuttle box unit 15 and the reserve shuttle box unit 15'. The picker stick 76 (see Fig. 14) is adapted to throw the shuttles 72 25 from the replaceable box unit 15 to the fixed double shuttle box 13 across the lay 62. As indicated in Fig. 13 the shuttles 72 are just being returned to the operating shuttle box unit 15, the refilling 275 having been placed in the warp by the 30 passage of the shuttles 72 therethrough and having been beat into position at the fell by forward movement of the reed 84.

As shown best in Fig. 13 the chain 105 connected to the long arm 234 of the multiplying lever passes over the rollers 106 and 107 and is connected to the central control rod 78 of the elevator structure.

As shown in Fig. 14, the crank 111 is connected to the ear 118a of the elevator frame by the crank 40 connector rod 110, the pick being formed and the shuttle being passed across the shed during the arc designated by the numeral 113 and the shuttles dwelling in their fixed double shuttle box 78 or the replaceable shuttle box unit 15 during the 45 arc 114. Several of these cranks 111 and crank connectors 110 are preferably provided to actuate and steady the reciprocation of the lay 62.

As shown in Figs. 13 and 14, (see also Fig. 17) the elevator frame consists of a U-shaped cast 50 element 276, with side members 287 and 288 provided with runways for guiding the elevator 11 75 and the operating and reserve shuttle box units 75 and 75'. The elevator is provided with a platform 278 directly under and closely adjacent to 55 the operating shuttle box 75. The lower portion of the elevator is provided with the bosses 279, 280 and 281 connected by the webs 282, which bosses respectively receive the guide rods 283, 78 60 and 284.

The side leg members 277 of the frame extend upwardly to the position indicated at 283 for the left side leg member 277 (see Figures 14 and 15) and to the position indicated at 284 (see Fig. 16) for the right leg 277 of the U-shaped frame 78. 65

To the front sides of the upright members 277 of the U-shaped elevator frame 78 are connected the side plates 285 and 286 respectively by the bolts 288 and 286 (see also Figs. 16, 21 and 22) and to the inside of these upright side members 70 277 are also connected the elevator side rails 287 and 288 by the screws 288 and 288 respectively. The upper portion of the side plate 285 has a rearwardly directed flange 289 which fits over the top of the side leg 277 of the frame 78. The 75

ends of the elevator 77 are provided with the rail portions 290 (see Figs. 21, 22 and 25) which fit in the grooves 291 in the side rails 287 and 297.

The double shuttle box unit shown in detail upon Figs. 27 to 31 rides in the grooves 299 and 300, in the inner edges of the side plates 285 and 295 on the right and left sides of the elevator frame 79, respectively.

Referring to Figs. 27 to 31, the shuttle box unit 75 has a body 330 preferably of cast duralumin which is provided with the recesses 331 (see Figs. 30 and 31) for receiving the shuttles, which are of trapezoidal shape to accommodate the shuttles 72, see Fig. 29, said shuttle being of corresponding parallelogram or trapezoidal shape to fit into the correspondingly shaped openings in the shed or warp (see also Fig. 7).

As shown in Fig. 31 the shuttle box unit 75 is provided with two L-shaped webs 332 at the lower and upper rear edges thereof and with a central T-shaped web 333, which webs are connected to form the body 330 at the right end of the box unit as indicated at 335, 336 and 350 (see Figs. 27, 29 and 30).

The shuttles are designed to enter these recesses 331 and run along the inside surfaces of the L-members 332 and the T-members 383, the forward sides of the shuttles 72 contacting with the brakes or swells 337. These swells 337, as in 30 the clevis 340, are pivotally connected by the rods 338 to the ears 339 at the left end of the body 330 of the box unit 75.

Each swell 337 is provided with a leaf spring 341, the rear end 342 of which is screwed at 343 to the left side of the body 330 of the shuttle box unit 75. Extensions 329 of these springs 341 are held between the bosses 344 on the left end of the body of the shuttle box unit 75, whereby the springs 341 are prevented from turning upon 40 their threaded connections 343. The right ends of the springs 345 being bowed inwardly to press against the swells 337 are received in the runway between the elevations 346 on the front of the swells 337. The right ends 347 of the swells 337 project between the ears 348 projecting horizontally forwardly from the right end of the shuttle box unit at 350 and these ears receive a pin 349, which limits the outward movement of the swell 337, as shown best in Fig. 27.

When the shuttles are out of position in the shuttle box unit the swells 337 are pressed by the springs 341 against the side 350 of the shuttle box unit construction. When the shuttles are in position, however, the swells 337 will be pressed out toward the stop pin 349 (as shown in Fig. 27, as if the shuttles were in the box unit).

Between the T-section 331 and the L-section 332 of Fig. 31 are the slots 351, which are adapted to receive the pickers, to be more fully described in connection with Figs. 22 and 23, which contact with the spurs 150 of the shuttles 72.

The left end of the shuttle box unit 75 is provided with the track 352, which fits in the slot 299 in the left side plate 285 and the right end of the shuttle box unit 330 is provided with the track 353 which fits in the slot 300 in the right side plate 295 of the elevator frame 79 (see also Fig. 22). The right side of the shuttle box unit is also provided with the outwardly projecting lip 354.

By placing the vertical tracks 352 and 353 at opposite corners of the shuttle box unit 330 so as to cooperate with the tracks 299 and 300 carried on the side plates 285 and 295 respectively of the U-shaped elevator frame 79 it is possible to obtain

a much better balance of the box unit when in position in the elevator frame and/or when moving into or out of position along the grooves 299 and 300.

When in operating position the shuttle box unit 330 is held by the pins 355 and 356, indicated in dotted lines in Figs. 28 and 29 respectively carried by the left and right plates 285 and 373 of the elevator U-frame 79 (see also Figs. 15, 16, 16a, 22, 23 and 24).

As shown in Figs. 22 and 23 it will be noted that the pin 355 projects into the track 299 from the plate 285 while the pin 356 projects below the extension 354 from the lower right front side of the plate 373.

As shown in Figs. 28 and 29 the lower edge 357 of the track 352 and the lower edge 358 of the extension 354 are flush with the bottom face 359 of the body of the box unit 330 so that the pins projecting therebelow will hold the box unit in 20 a predetermined position.

When in succession the shuttles 72 have become exhausted, the circuit has been closed in the fixed double shuttle box 73 and the shuttles 72 have been shot back to the removable box unit 75, the elevator 77 will then be lowered out of position and in lowering will cause removal of the pins 355 and 356 from under the track 352 and the extension 354 of the shuttle box unit. As the box unit 75 slides down in the grooves 299 and 300 to rest upon the platform 278 of the elevator 77, the pins 355 and 356 will again be released upon further lowering of the elevator 77 and will be returned by the resilient springs 360 indicated in Figs. 22 and 24. As soon as the point 361 on the track 352 and the point 362 on the extension 354 of the box unit (see Figs. 28 and 29) have passed, the pins 355 and 356 will shoot back into position readily to catch and hold the reserve box unit 75 in proper operating position.

The pins 355 and 356 are of substantially identical construction and may be conveniently described in connection with Fig. 24 which is a top horizontal section, on the lines 24—24 of Figs. 17 and 23.

As shown, the projecting portion of the pin 355 fits in a bore 363 in the side plate 285, which bore is enlarged at 364 to receive the enlarged shoulder portion 365. The resilient spring 360 reacts between the enlarged shoulder portion 365 and the shoulder 366 to the rear of the enlarged bore 364. The spring 360 is guided upon the pin extension 367, which fits in a bore 368 to the rear of the enlarged opening 364.

The enlarged shoulder portion 365 is pressed 55 against a shoulder 369 by the spring 360 to cause the pin to project under the track 352 of the box unit 75. The forward side of the enlargement or shoulder portion 365 is provided with a pin 370 which rides in the slot 371, said pin enabling withdrawal of the pin 355 to release the box unit 75 containing the exhausted shuttles 72.

As has been already described, the left pin 355 is carried in the left front plate 285 bolted to the left leg 277 of the U-frame 79. On the right side 65 of the frame 79 the pin 356 is carried in the boss 372 held by the flange 328 extending rearwardly from the side plate 373.

The front plate 373 (see Figs. 13, 16, 16a, 21 and 22) is bolted at 374 to the wood extension 70 375 of the lay member 62b.

The front end 425 of the pin 370 (see Figs. 17 and 24) on the left side of the frame 79 is received in the slot 426 (see also Figs. 13 and 15) in a boss 427 at the upper end of the lever 428 which rides 75

at its lower end upon the shaft or pivot rod 429 fixed in the boss 430 projecting forwardly from the left side plate 285. The lever 428 is actuated, moving the end of the pin 425 to the left by the cam finger projection 431. This finger 431 projects inside of the left frame member 277 and is adapted to contact with the pawl 432 at the end of the elevator 77. The similarly functioning elements on the other side of the elevator frame 10 are indicated by the same numerals primed (see particularly Figs. 16 and 16a).

The pawl 432 (see particularly Fig. 17 and also Figs. 13, 21 and 22) is pivotally connected at 433 below an outwardly extending shelf 434 on the 15 forward side corner of the elevator platform 278. This shelf 434 acts as a stop to prevent the pawl 432 from moving upwardly from its position in Fig. 17, so that when the elevator 77 descends, the pawl 432 will press the finger 431 inwardly, moving the pin 355 inwardly and releasing the double 20 shuttle box unit 75, which thereupon will drop down upon the upper platform 278.

The pawl 432 is resiliently held against the stop 434 by the spring 435.

Upon the return upward movement of the elevator, after the new box unit 75' has been moved into operating position, the pawl 432 will contact the lower end of the finger 431 and will be rotated downwardly. It will thereupon slide past said finger 431 without moving it and effecting the 30 location of the pins 355 and 356, holding the new shuttle box unit 75' in position.

The elevator 77 in its further descent beyond the finger 431 will cause the pawl 432, as indicated on Fig. 17, to contact with the finger 436 to release a new reserve box unit 75' from the magazine 83 and permit it to slide into the upper portion of the elevator frame 79, forming the new reserve box unit, which will be ready to be placed 40 in operating position after the shuttles of the new box unit 75' have been exhausted.

The magazine 83 depends from the loom frame 459 through the hanger member 460 (see particularly Figs. 13 and 14 and also 15, 16, 16a and 45 19) which is received in a sleeve 461 having a narrowed portion 462 pivotally connected between the clevis jaws 463 of a hanger support 464.

By this connection the magazine 83 may be swung forwardly but is stopped from rearward 50 pivotal motion by the stop member 465, which is contacted by the adjustable screw 466 in the rearwardly projecting ear 467 from the narrowed portion 462. The hanger 460 at its lower end receives the collar 468 fixed thereupon 55 by the set screws 471. The collar 468 has the rearwardly projecting ear 469 to which is connected a spring 470 (see Fig. 14) for holding the magazine 83 so that the adjustable screw 466 will be in contact with the stop 465.

The collar 468 (see particularly Figs. 14 and 19) is provided with a forward extension 472, to which is bolted the flange 473, by the bolt 474.

The flange 473 extends rearwardly from the main traverse member 475 of the magazine. To 65 the ends of the traverse member 475 (see Figs. 14, 15, 16 and 19) are bolted at 476 the side frame members 478 and 479, which carry the tracks 480 and 481 for receiving the cooperating tracks 352 and 353 of the shuttle box units 75', 75³, 75⁴ and so forth. Any suitable number of box units may be held in the magazine 83 and in the tracks 480 and 481, depending upon the height of the upward extensions 482 and 483 of the tracks 480 and 481 (see Figs. 14, 15 and 16).

75 The lowermost shuttle box unit 75' in the

magazine 83 will be held in position by the hooks 484 and 485 (see Figs. 13, 14, 15, 16, 17, 19 and 20).

The upper portion of the hooks 484 and 485 are provided with the transversely extending flanges 486 and 487, which are connected by bolts 488 respectively to the side frame members 478 and 479 of the magazine 83.

It will be noted that the depending arms 489 and 490 of these hooks (see particularly Figs. 10 13 and 17) locate the rearwardly extending horizontal flange portions 491 and 492 (see Figs. 14, 16, 19 and 20) so that they will respectively support the shuttle box unit 75' on its left extension 493 inside of the track 352 and on its 15 right extension 354 (see Figs. 19 and 20).

Extending between the vertical depending arms 489 and 490 of the hooks 484 and 485 respectively, the lower horizontal box unit supporting portions 491 and 492 are the inclined 20 connecting webs 493 and 494, which serve to position the box unit 75' rearwardly upon the ends of the hooks 484 and 485 from which it may be readily removed during the shuttle changing operation to move into the elevator 25 frame 79 and become the new reserve box unit.

As shown in Figs. 15 and 16 the main tracks 480 and 481 substantially terminate at the lower edges 496 and 497 of the side frame members 478 and 479 of the magazine structure 83. As 30 a result the lowermost shuttle box unit 75' will have dropped out of the web tracks 480 and 481 of the magazine structure when it is resting upon the horizontal portions 491 and 492 of the hooks 484 and 485.

The upper portion of the tracks 352 and 353 of the box unit 75' (see Fig. 20) will be held in the race-shaped openings 498 and 499 formed between the track extensions 500 and 501 and the holding lever fingers 502 and 503. The 40 races 498 and 499 will constitute continuations of the races or tracks 480 and 481 in the main 35 magazine structure.

The levers or fingers 502 and 503, indicated in small scale in Figs. 13 and 14, 15 and 16, are 45 shown in detail in Fig. 20. The fingers 502 and 503 are supported respectively upon the projecting portions 525 and 526 which carry the pivot rods 527 and 528. The clevises 529 of the fingers 502 and 503 ride upon the pivot rods 527 50 and 528. The pivot rods 527 and 528 between the jaw of said clevises 529 receive the coil springs 530. One end 531 of these coil springs 530 contacts with the downwardly depending extensions 500 and 501 of the side frames 478 55 and 479 of the magazine structure, while the other end 533 presses against the side portion of the finger 534 beyond the clevis portions 529.

The extensions 500 and 501 are provided with the outwardly projecting stops 535 which contact with correspondingly shaped stops 536 on the fingers 502 and 503 to position properly the fingers 502 and 503 when they are pressed home by the coil springs 530. The ends of the fingers 537 form the rear sides of the tracks or races 65 498 and 499.

As the elevator 77 continues its descent, after having released the shuttle box unit 75 by withdrawing the supporting pins 355 and 356, the elevator will continue its descent until the trip 70 latch 432 presses upon the finger 436, which will through a series of levers actuate the slidable box unit removing elements 545 and 545'. When the elevator frame structure 79 has completed its forward movement and the operating shuttle box unit 75 has been lowered out of position, 75

the lowermost shuttle box unit 75² in the magazine structure 83 will be carried off the hooks 484 and 485 and dropped into the elevator frame 79 as a new reserve box unit.

5 The operation of this box unit removing mechanism will be particularly described in connection with the left hand arrangement, similarly functioning parts on the right hand side of the elevator frame 79 being designated by 10 the same numerals primed.

Referring to Figs. 13, 14, 15, 16, 17 and 21, the finger 436 is provided with a hub 546 which is pivoted at 429 on the same pivot rod as carries the pin-removing lever 428. From the hub 546 15 projects outwardly the extension 547 (see particularly Fig. 17) which is pivoted at 548 to the substantially vertical link 549 which may be made of adjustable length by a turn-buckle arrangement, if desired.

20 The upper portion of the link 549 is provided with a hub 550 carrying the pin 551 which projects into the slot 552 in the crosshead 553 in the bell crank lever 554 having the horizontal arm 555 and the vertical arm 556. The lever 25 554 is pivotally connected at 557 to the side plate 285 (see Figs. 13, 14, 15, 16 and 21). The upper end of the bell crank lever 554 is pivotally connected at 558 to the slide member 545.

25 The slide 545 is shown in relatively small scale in Figs. 13 and 14, in somewhat larger scale in Figs. 15, 16 and 17, and in still more enlarged scale in Fig. 18.

30 The slide 545 is provided with the wedge-shaped openings 575 on its back face with slides 35 upon the corresponding track 576 carried on the upward extension 577 of the left side plate 285.

35 The inside end of the slide 545 carries the rearwardly turned portion 578 (see Fig. 18) which is normally held by the bell crank lever 554 and by the spring 554a (Fig. 17) in retracted position as indicated by the dotted lines at 579, (Fig. 18). When in retracted position as indicated at 579, it will be noted that its inside face 580 will pass outside of the outer end of the track 352 at the 40 end of the shuttle box unit 75² in the magazine.

45 When, however, moved inwardly through the bell crank lever 554, the face 581 will contact with the forward side of the track 352 and will be in the position to move the lowermost shuttle box 50 unit 75² rearwardly so that it will slide downwardly into the elevator frame structure 79 as a new reserve box unit.

55 The finger element 582 (see Fig. 18) cooperates with the slide 545 to remove said lowermost box unit 75² from the magazine structure into the elevator frame structure and its face 583 contacts with the rear side of the track 352. The finger 582 is provided with a clevis 584 which is pivotally connected on the pin 585 supported upon the shelf 586. The lug 587 on the finger 582 is provided with a bore receiving the shank of the bolt 588. The bolt 588 is threaded into the boss 589 in the upper extension 577 of the left front plate 285. The nuts 590 and 591 screwed onto said bolt 588 serve to position the finger 582 in a pre-determined location.

60 When the box unit changing mechanism is not being actuated and the elevator 77 is fixed in its uppermost position, as shown in Fig. 13, the finger 582 will merely come up each time the lay moves forwardly to the limit of its forward stroke against the box unit 75² on the elevator and press it forwardly upon the magazine hooks 484 and 485.

65 75 Any contact between the finger 582 and the

track 352 of the lowermost magazine shuttle box 75² is taken care of most satisfactorily by relative forward movement between the magazine 83 and the loom frame on the pivotal axis 463 at the top of the hanger rod 460 against the spring 470.

5

Preferably, the magazine frame 83 is held by the spring 470 against an adjustable stop 466 in such a position that it is inclined very slightly downwardly and rearwardly instead of being in vertical position (see Fig. 14). When the finger 10 582 of Fig. 18 at 583, contacts with the track 352 of the shuttle box unit 75² before the lay 62 has completed its forward movement, the magazine frame 83 will be swung slightly forwardly, extending the spring 470 of Fig. 14.

15

It is therefore apparent as the elevator is lowered, so that the latch 432 presses inwardly upon the finger 436, the lever arm 547 and the vertical arm 549 (see particularly Figs. 13 and 17) will be elevated and the arm 556 of the bell crank lever 20 554 will be moved inwardly against the spring 554a at the same time moving inwardly the slide 545.

The elevator 77 will reach the position of the finger 436 just before the lay 62 has achieved its extreme forward position, preferably at the instant when the finger 582 makes contact with the track 352, and will pause there slightly so that the inwardly turned portion 578 of the slide 545 will contact with the front side of the track 352 on the shuttle box unit 75², as indicated in Fig. 18.

30

While the latch 432 on the end of the elevator 77 is still in contact with the finger 436, the lay 62, together with the elevator frame 79, will start its rearward movement, carrying the lowermost magazine shuttle box unit 75 rearwardly. During this 35 operation the fingers 502 and 503 of Fig. 20 will be moved rearwardly, releasing the upper ends of the tracks 352 and 353 of the box unit 75², the position of the fingers 502 and 503 when retracted to permit removal of the shuttle box 75² being 40 shown in dotted lines in Fig. 20. The lowermost magazine box unit 75² will thus be carried rearwardly in the elevator frame 79 and next magazine box unit 75³ will slide down in position upon the hooks 484 and 485.

45

While the lay 62 is moving rearwardly with the elevator frame 79 carrying the new reserve box unit 75² the elevator 77 will continue its descent until it has achieved its lowermost position and is positioned substantially in the L-shaped bottom 50 rail 276 of the elevator frame 79.

When the elevator frame 79 again moves forwardly with the lay 62 to its extreme forward position the ejector mechanism will be actuated to remove the exhausted shuttle box unit 75 resting 55 upon the elevator platform 278 and then the elevator 77 will again be lifted to its normal elevated position directly below the new operating shuttle box unit 75¹. The mechanism for removing the shuttle box unit is shown in small 60 scale in Figs. 15, 16 and 17 and is shown in detail in Fig. 25.

Fig. 25 indicates in solid lines the position of the lower portion of the elevator frame 79 which receives the elevator 77 carrying the exhausted 65 shuttle box unit 75, when the lay 62 is in its extreme forward position and the exhausted shuttle box unit 75 is about to be removed from the elevator. The dotted lines shown in the upper portion of Fig. 25 indicate the elevator frame 79 70 carrying the elevator 77 in retracted position upon the next rearward movement of the lay with the exhausted shuttle box unit 75 removed.

Referring to the solid line portion of Fig. 25 it will be noted that the tracks 352 and 353 re- 75

spectively at the left forward and right rear edges of the shuttle box unit 75 have dropped out of the tracks carried in the left side plate 285 and the right side plate 295 attached to the left and right sides of the elevator frame respectively, these track carrying plates terminating adjacent to the position of the fingers 436 which cause the lowest magazine box unit 75² to be transferred into the elevator frame structure 79.

As the elevator frame 79 moves forwardly with the exhausted box unit 75 in its lowermost position, the latches 600 pivotally connected at 601 to the supporting frame of the loom will be snapped outwardly against the leaf springs 604.

The edge of the track 352 and the edge of the extension 354 will slide over the sloping inside faces 605, moving the latches 600 outwardly, until the shoulders 606 are reached, when the latches 600 will be snapped inwardly by the spring 604. This latch 600 will then hold the exhausted shuttle box unit 75 so that it cannot be moved rearwardly with the elevator 77 upon the next rearward movement of the lay 62.

As indicated in Fig. 25 the hub 607 of the left hand latch is provided with a forward extension 608 receiving the adjustable stop screw 609 which contacts with the stop 610 to regulate the position of the left hand latch 600.

As shown best in Figs. 14 and 15, the supporting structure 602 carrying the pivot rod 601 is provided with a lateral shelf 611 with a forward vertical flange 614. The flange 614 is bolted at 613 to the lower end 612 of the depending bracket 615 (see particularly Fig. 14). The upper end of the bracket 615 is bolted at 616 to the L-shaped frame member 617 which serves as a table for the transversely reciprocating carrier element 618 which carries the blade 61 (see also Fig. 16).

The other latch member 600 (see Fig. 25) is provided with the forward extension 619 from its hub 607 which contacts with the adjustable stop screw 620 held by the locknut 621 on the lug 622. The pivot rod 601 is carried from a shelf 623 which is provided with the downwardly extending flange 624 which is bolted at 625 to the loom frame side structure 626, (see particularly Figs. 16 and 16a).

It is therefore apparent that the latches 600 will hold the exhausted shuttle box until 75 so as to remove it from the platform 278 from the elevator 77, so that the elevator 77, as shown in dotted lines in Fig. 25, will be free to ascend to its normal uppermost position, as shown in Fig. 13.

As soon as the box unit 75 has been removed from the platform 278 of the elevator, it will be free to fall downwardly from the latches 600 into the hopper 640 and then into the magazine 641, shown in Figs. 35 and 36 and also in Fig. 14.

The hopper 640, as shown in Figs. 14, 35 and 36, is inclined downwardly from the right end and is supported at its forward edges by the brackets 642 extending upwardly from the support 643 (see particularly Figs. 14 and 35).

The hopper is provided with the downwardly and forwardly inclined rear sheet metal wall 644, with substantially vertical front sheet metal walls 645, with the left vertical side sheet metal walls 646, and the curved right end 647, which curved portion guides the right edge of the box unit 75 after it has been dropped by the latches 600.

The open top 648 of the hopper 640 inclines downwardly and rearwardly to receive the box unit 75, when it is dropped and the bottom of the hopper 649 has a forward and downward slope,

as well as being sloped downwardly to the left, so that the box unit upon dropping into the hopper 640 will slide downwardly to the left and then cut through the opening 650 in the lower part of the front wall 645. The opening 650 is partly closed by the depending gate 651. The gate 651 is hinged upon the rod 652 held on the lower portion of the sheet metal wall 645, said rod being provided with the coil spring 653 to press the gate closed to obstruct the opening 650.

The resiliently closed gate 651 will only be opened by the weight of the exhausted shuttle box unit 75, when it has completed its sliding movement to the left along the inclined bottom 649. At this time the entire weight of the box unit 75 will press forwardly upon the gate 651 due to the inclination of the bottom 649 of the hopper 640, with the result that the gate 651 will open and permit the box unit to drop into the magazine 641.

The magazine 641 consists of a platform 654, the ends of which are provided with the sleeve members 655, which ride upon the rod 656 connected at the flanges 657 to the support 643. The sleeves 655 are attached to the tensioned coil springs 658 which are connected at their upper ends to the collars 659 and the top of the slide rod 656, said springs 658 being extended due to the weight of the magazine 641 and the exhausted shuttle box units 75 therein. The front side of the elevator is provided with the upwardly extending vertical members 660, which hold the exhausted shuttle box units 75 from falling forwardly out of the magazine structure 641.

As each shuttle box unit falls out of the elevator frame 79 into the hopper 640 and then into the magazine 641, the magazine 641 will be lowered sufficiently under the added weight, so that the top of the exhausted shuttle box unit received therein will be below the opening 650. As a result the next exhausted shuttle box unit 75 may conveniently slide through the hopper 640 and then drop into the magazine 641.

This new box unit will again lower the magazine platform 654 sufficiently so that the top of the box unit will again be below the hopper opening 650. At convenient intervals the weaver in charge of the loom may remove the exhausted shuttle box units from the magazine 641 for replenishment, whereupon the platform 654 of the magazine will move up to its normal uppermost position (indicated in solid lines in Figs. 14 and 36) with the platform 654 directly below the opening 650 in the hopper 640.

As has been previously described, particularly in connection with Figs. 22 and 23, the pin 355 on the left side of the elevator frame 79 and the pin 356 on the right side of the elevator frame 79, are retracted upon lowering of the elevator 77, whereupon the exhausted shuttle box unit 75 will drop down upon the platform 278 of the elevator 77.

However, just before the pins 355 and 356 have been released, the shuttles have been shot into the operative shuttle box unit 75 from the right side of the loom and the spurs 150 at the left ends of the shuttles 72 will have been received in the depressions 670 of the pickers 671. These pickers 671, one being provided for each shuttle 72, may be made of compressed non-metallic material (see particularly Figs. 22 and 23) and they are provided with central web 672 with elongated rounded enlargements 673 at their forward ends and similar enlargements 674 at their

rear ends, which extend the full width of the picker 671.

The enlargements 673 at their right ends are provided with the depressions 670 which receive 5 the spurs 150 of the shuttles 72 and the rear ends 674 of the pickers are provided with the longitudinal or cylindrical openings or bores 675, which slide upon the picker rods 676 extending entirely across the back of the elevator frame structure, 10 as shown also in Figs. 15, 16, 16a and 21. The ends of these picker rods 676 are received in the lugs 677, which may be cast integrally with the elevator frame casting 79.

As shown best in Fig. 23, the webs 671 pass 15 through the slots 678 in the rear of the elevator frame 79 (see Fig. 23). These webs 672 are received in the slots 351 of the shuttle box unit 75 upon leftward movement of the pickers 671. Received in the openings 679 in the webs 672 of 20 the pickers is the upper end 680 of the picker stick 76, the upper end 680 of said picker stick passing through openings 679 in both pickers.

As previously explained, the spurs 150 of the ends of the shuttles 72 will be thrown into the 25 cavities 670 of the pickers 671. In order to enable release of the spurs 150 of the exhausted shuttles 72 from the pickers 671, upon release of the pins 355 and 356, it is necessary to move the pickers to the left to release the spurs 150 of 30 the shuttles 72.

In the embodiment shown this is accomplished by providing a rod 681 (see Figs. 13 and 26), which is connected to the platform of the elevator at 682, and projects downwardly through 35 an opening in a lug 683 in the lower portion of the elevator frame 79.

As shown best in Fig. 26, the picker stick 76 is provided with a plate 684 which contacts with the nose 685 to limit the leftward movement of 40 the picker 671 by the spring 686 (see also Fig. 13). The spring 686 is connected at one end 687 to the support of the loom and at the other end 688 to the sector member 689, which is bolted to the picker stick 76, as indicated at 690 by the 45 downwardly extending flange 691.

On the top of the quadrant is received the strap 692, which is actuated by the bell crank lever 693 and the cam 693a to pull the picker stick 76 over with a sudden jerk, causing the 50 pickers 671 to be propelled through the slots 351 in the shuttle box unit 75 and the slots 678 in the frame 79, whereby the shuttles 72 are propelled and thrown to the fixed double shuttle box 73 on the other side of the loom.

55 Referring to Fig. 26, the stop 685 is pivotally connected at 694 in the bracket 695, depending from the elevator frame and is provided with a spring 696 connected to an ear 697 to press the upper side of the stop 685 against the pin 697a. Also connected to the pivotal connection 694 is 60 the plate 698 which upon descent of the elevator 71 is moved downwardly by the lower end 699 of the rod 681.

When the rod 681 descends with the elevator 65 71, the stop 685 will be rotated clockwise as shown in Fig. 26 to the position indicated in dotted lines, permitting the picker stick to be moved farther to the left by the spring 686 of Fig. 13, which will in turn move the pickers 671 of Figs. 22 and 23 70 farther to the left and release the spurs 150 of the shuttles 72.

The contact between the end of the stop 685 in the plate 684 should be such that the picker stick 76 will tend to move the rotatable stop 685 upwardly against the pin 697a, so that assurance 75

is had during the normal operation of the loom that the stop 685 will not be rotated clockwise until the elevator 71 is actuated.

Fig. 37 is a detail of the elevator lowering and elevating rods which are shown in small scale 5 in Figs. 13 and 14. In Fig. 37 to the end of the lay rocker shaft 63 which is pivotally mounted in the chassis frame member 720, is connected the elevator-frame carrying member 721. This member 721 is connected to the end of the lay 10 rocker shaft by means of the collar 722 provided with the set screw 723. The frame 721 is shown in front view in Figs. 13 and 37 and in side view in Fig. 14, and as shown is provided with the outwardly extending lug or ear 724 which enables 15 the pivotal connection 725 to the picker stick 76. The member 721 also carries the rearwardly turned flanges 726 and 727, which rigidly carry the tubular members 728 and 729. The bracket 727 is also provided with a bearing opening 730 20 which receives a slidable tube 731.

The tubular members 728 and 729 which are attached rigidly to the flanges 726 and 727 project upwardly and at their tops are connected rigidly to the bosses 732 and 733 at the bottom 25 of the elevator frame 79, whereby said elevator frame is supported from the structure 721. These tubular members 728 and 729 receive the rods 283 and 284 which are provided with guide bearings 734 in the upper part of the tubular member 30 728 and 729.

The lower ends of the rods 283 and 284 receive the springs 735 which are connected and react at their lower ends against the enlargements 736 on the lower ends of the rods 283 and 284. As 35 shown in Fig. 37, the springs 735 are expanded to their full length, but when the elevator 71 is raised these springs 735 will rise upwardly with the rods 283 and 284 and will be compressed at their upper ends against the guide bearings 734. 40

During the time when the elevator 71 is in its uppermost position, these springs 735 will be substantially compressed, so that when the elevator 71 is lowered they will hasten the earlier movements thereof, assuring quick release of the 45 exhausted shuttle box unit 75 and lowering of it from its operating position, so that the reserve box unit 75' may quickly take its place.

The lifting rod 78 of the elevator is provided with an encircling coil spring 737 which reacts 50 at its upper end against the boss 280 and at the lower end against the collar 738. The collar 738 is rigidly connected to the lower end of the tube 731 and may slide upon the rod 78. The upper end of the tube 731 above its bearing 730 is provided 55 with the flange 739, which has the outwardly projecting ear 740 having an eye 741, which receives the end of the linked chain 105.

When the chain 105 is drawn to the right the sleeve 731 will be drawn upwardly and through 60 the spring 737 will lift the elevator 71. Thus if the box unit 75 has not been taken away by the ejector finger 690, shown in Fig. 25, no damage will be caused by the elevator 71 carrying the exhausted box unit 75 upwardly again. In 65 such an instance, the spring 737 may compress and permit the elevator to assume a relatively lower position to accommodate the exhausted shuttle box unit 75 below the new operating shuttle box unit 75'.

70 Referring to Figs. 10 and 13, upon release of one of the triggers 167 of Figs. 8 and 9 in one of the shuttles 72 in the right hand double shuttle box 73, the latch 96 will be released, when the contact face 213 of the circuit breaker 85 presses 75

against the spring fingers 86 closing the circuit through the electromagnet 87. This will permit the cam follower roller 88 to follow the contour of the cam 84.

- 5 When this occurs the roller 88 is between the positions 750 and 750'. The shuttles reach the right hand double shuttle box at 750 and leave it at 750'. The lay will be moving forward when the shuttles enter the right hand fixed double shuttle box at 750 and it will continue to move forwardly until the point 751, when it will start to move to the rear.
- 10 When the lay is still advancing towards the front of the loom, the finger 92 will not fully engage the tooth 93 until just before the lay has reached its extreme forward position. This position on the cam will bring the cam roller to approximately the point 751 on the cam. As the lay recedes from the front towards the back of the loom, the finger 92 is engaged by the tooth 93 and the latch 96 and 97 is gradually becoming disengaged until the lay has advanced towards the rear of the loom to the picking point 750' or bottom center on the lay actuating crank shaft.
- 15 At the point 750', the latches 96 and 97 will be fully disengaged and consequently allow the cam roller 88 to follow the cam contour from this point onward.

From 751 to 752 the lay will move rearwardly, reaching the limit of its rearward movement at 752 and from 752 to 753 the lay will again move forwardly until it again achieves its most forward position at 753. After the lay has moved from the position of 751 and before it achieves the position of 753 and while it is crossing the position 752 the shuttles 72 are thrown by the picker stick 74 from the fixed double shuttle box 73 into the removable shuttle box unit 75, which shuttle box unit 75 is about to be taken out of operating position to be replaced by the reserve box unit 75'.

When the point 754 on the cam 84 reaches the roller 88, the shuttles 72 will have already been received in the left hand box unit 75 and the roller 88 will then quickly move centrally over the steeply inclined portion 755 of the cam 84.

As a result, the chain 105 will permit the elevator 77 to lower quickly until the latches 432 come into contact with the fingers 431 causing the pins 355 and 356 to be withdrawn (see also Figs. 13, 22 and 24). At the same time the rod 681 (see Figs. 13 and 26) will press downwardly on the plate 698, to allow the pickers 671 (see Fig. 22) to move to the left, releasing the spurs 150 of the shuttles 72. This will altogether release the exhausted shuttle box unit 75 and permit it to drop onto the elevator platform 278, which is now a short distance below the shuttle box unit 75 due to the movement of the roller 88 over the steeply inclined portion 755.

This descending motion of the elevator 77 will be hastened by expansion of the compressed springs 735 (see also Fig. 37) which have been compressed upon previous ascension of the elevator 77. The descending movement is primarily caused by the weight of the elevator 77. The motion of the roller 88 in passing over the inclined portion 755 of the cam 84, will be greatly multiplied by the cam lever 100 and the bell crank lever 103, (see also Fig. 12), which levers respectively have a multiplication of 5 1/2 to 10 and 2 to 3 in the embodiment shown, resulting in a total multiplication of 1 to 2.73.

After passing over the steeply inclined portion 755 which will result in the pins 355 and 356

and the pickers 671 being moved to release the exhausted shuttle box unit 75, the roller 88 will then pass over the dwell portion 756 and then onto the more gradually sloping portion 757. The approximate position of the elevator when the roller 88 is on the portion 756 will be in the position as indicated by dotted lines in Fig. 17.

The roller 88, during its movements over the gradually declining portion 757 and the cam 84, will cause the latch 432 to press upon the finger 10 436, moving the slide 545 inwardly (see also Figs. 17 and 18) causing said slide flange 578 to grab the track 352 of the box unit between the fingers 582 and 578. It will be noted that this occurs approximately while the lay 62 is in its extreme forward position, as indicated at 753.

Then as the lay moves rearwardly from the position indicated at 753, the lowermost magazine box unit 752 will be carried rearwardly with the elevator frame 79 and will drop into position on top of the new operating box unit 75'.

Then the roller 88 passes onto the sloping portion 760 of the cam which is less steeply inclined than the portion 755, but more steeply inclined than the portion 757, so that the elevator will be lowered to its extreme lowermost position, as shown in the solid lines in Fig. 25, and in Fig. 37. While this is occurring the lay is moving forwardly from the position at 759 to its most forward position at 761, the roller 88 passing onto the dwell portion 762 of the cam. While the roller 88 is on the dwell portion 762 of the cam the latches 600 (see also Fig. 25) will grasp the track 352 and the extension 354 of the box unit 75, whereby the box unit 75 will be subsequently removed and dropped into the hopper 640 and then onto the magazine 641 (see Figs. 35 and 36) while the elevator frame 79, together with the lay 62, is moving rearwardly to the dotted line position shown in Fig. 25.

40

During the next pick, when the lay is moving rearwardly to 763 and then forwardly again to the position at 764, the roller 88 will pass from the dwell 762 and then upon the ascending portion 765 of the cam, while it is moving the elevator 77 upwardly through the cam lever 100, the chain 101, the bell crank lever 103 and the chain 105. The roller 88 will now be in the position shown in Fig. 10, the box unit 75 will have been changed and the weaving will continue without intermission until the next box unit changing operation.

The small depression 766 on the cam of Fig. 10 is for the purpose of enabling more ready interlocking between the latches 96 and 97 to retain the roller 88 elevated from the depressed portion of the cam 84 until the next box unit changing operation.

Referring to Fig. 10 and also to Figs. 2 to 5, if the total movement of the crank to complete one revolution or one pick is divided into 16 parts, the 60 shuttle 72 will fly across the shed during $\frac{1}{16}$ ths and will dwell in the shuttle boxes during $\frac{1}{16}$ ths of the total travel of the crank.

It therefore follows, referring to Fig. 10 that the quadrants between the points 751, 753, 761 and 764 when the lay 62 is in its foremost position may be similarly divided into 16 parts and that the shuttles will fly across during $\frac{1}{16}$ ths of each quadrant before and after the lay 62 is in its extreme rear positions 752, 759, 763 and 910. The 70 shuttles 72 are thrown across the shed after the lay has started backwards and not received in their boxes 73 or 75 until the lay is again moving forward after having reached its extreme rear position. The movement of the shuttles 72 dur- 75

ing the movement of the cam 84 is indicated by the arcs 900 of Fig. 10.

When the exhausted shuttle box unit 75 is removed from its position in the magazine 79 it will leave two filler threads in position at the fell of the cloth, which will extend over to the shuttles and should be cut in order to enable complete release of the exhausted shuttle box unit.

This is accomplished by means of a cutting device 780 shown on a small scale in Figs. 13 and 14 and in detail in Figs. 16a, 16b and 16c.

The knife 780 is provided with a holder portion 781 which receives the razor blade element 782, said razor blade element 782 being inclined, so that the last filler threads which have been beaten up to the fell 275 (see Fig. 13) will slide upwardly along the sharp edge of the blade 782 and will be most readily cut. The blade carrier is provided with the sleeve 783, see particularly Figs. 16b and 16c, which is held in position on the rod 784 by the set screw 785. The rod 784 extends into the sleeve 783 supported on the transverse rod 786. The rod 786 slides in the bore 787 in the bracket member 788 attached to the loom structure. The rod 786 is normally held in retracted position, so that the knife 782 will be forward of the fell by engagement of the pin 789 with the notch 790.

The pin 789 is provided with an enlargement 791 which rides in the bore 792, said enlargement being provided with the outwardly projecting pin 793 which rides in the slot 794 to maintain the pin 789 in position and guide its movement. The shank 795 projects upwardly into the base 796 of the clevis 797 over which is attached the coil spring 798 by the screws 799.

Projecting into the open space between the jaws of the clevis 797 and below the spring 798 is the bent rod 800, which rod 800 is connected to and moves with the arm 555' of the bell crank lever 554', which serves to actuate the slide 545' (see also Fig. 13) to cause removal of the lowest magazine shuttle box unit 75² from the magazine 83.

When a shuttle box unit is not being changed, the end of the extension 800 will ride into the open space between the clevis jaw and below the spring 798 without affecting the interlocking engagement of the pin 789 and the notch 790.

When, however, the box unit changing mechanism is being operated the element 555' of the bell crank lever 554' will be elevated, lifting the rod 800 and the spring 798, which will release the pin 789 from the notch 790. As a result the spring 801 which is compressed between the elements 785 and the frame 788 will move the knife 782 rearward where the knife 782 will come in contact with the two filling threads at the fell.

During this interval the lay 62 will be moving rearwardly and the rod 800 will be moved from under the spring 798 and the pin 789 will snap into a second notch 791' locking the rod 786 in extended position. Upon the next forward movement of the lay 62 a portion of the elevator frame structure 79 indicated at 802 will contact with the bumper 803 (see Fig. 16b), whereupon the rod 786 and the pin 795 will again interlock at the notch 790. The knife 782 will then be held out of position forward of the fell until the next box unit changing operation.

To assure that the shuttles are in proper position in either the shuttle boxes 73 and 75 during the operation of the loom, when the lay 62 is in its most forward position, a dagger arrangement is utilized which is shown diagrammatically upon Figs. 6, 7 and 13.

75 In the embodiment of the present arrangement,

specifically illustrated and described, to this dagger safety arrangement is connected another safety arrangement which will assure that the shuttle box unit 75² and 75', after the changing operation, have correctly moved into their new position. 5

To describe briefly the dagger mechanism, referring to the right hand double shuttle box as shown in Figs. 6 and 7, the swells 153 are normally pressed into the recesses 152 in the right hand double shuttle box 73, which recesses are adapted 10 to receive the flying shuttles 72. These swells 153 function approximately the same as the swells 337 on the replaceable shuttle box units 75, described in connection with Figs. 27 to 31.

The swells 153 are pressed inwardly through the 15 openings 148 in the rear of the fixed double shuttle box 73 by the leaf springs 149. The swell springs 149 are fastened directly to the outside of the double shuttle lay box and serve to keep a tension on the swells 153 and to press them partially inside 20 the boxes when the boxes are not occupied by their shuttles. The supporting structure 145 serves to lock the shuttles 72 in place in their double shuttle box after they have entered the same. The structure 145 swings into and out of position 25 on the shaft 144 and is operated by lever 155 which in turn is operated by the crank shaft connecting lay link (not shown). The shaft 144 is carried by the bracket 143. The end of each swell 153 beyond contact thereof with the leaf springs 149, 30 contacts with the contact pieces 154 of the dagger levers 155, one of which extends downwardly and is connected to the upper dagger shaft 142, and the other end of which is connected to the lower dagger shaft 157. 35

These dagger shafts 142 and 157 extend entirely across the loom and are connected through a link motion (see Fig. 34) at the other side of the lay to the upper and lower dagger shafts 824 and 825 (see Fig. 13) which are respectively connected 40 to the levers 826 and 827 contacting with the swells 337 of the shuttle box unit 75 (as shown in Figs. 27 to 31).

These link motions of Fig. 34 are required in view of the fact that in the fixed double shuttle 45 box unit 73, a rearward movement of the swells 153 elevates the dagger 156 into the safety position, while in the replaceable shuttle box unit 75, a forward movement of the swells 337 has the same effect. 50

Referring to Fig. 34, it will be noted that the shaft 825 is provided with the rearwardly extending lug 828, while the main dagger shaft 157 is provided with the forwardly projecting lug 829. The lug 828 is preferably slotted (not shown) to receive the pivotal connection 830, which is attached to the lug 829. It is therefore evident that a forward movement of the dagger lever 827 on the left side of the loom will move the shaft in the direction of the arrow 831, elevating the dagger as will also a rearward movement of the lever 154 at the right side of the loom. 60

Each shaft 142 and 157 carries a dagger at each side of the loom, only one dagger on each shaft 65 being shown.

The daggers 156, when in lowered position, as will also the other daggers, contact with the bumper 159 (see Fig. 7) and will throw out the operating mechanism of the loom 156a, 156b, 70 156c and 156d (see Fig. 14), upon forward movement of the lay 62, if either one of the shuttles 72 is not in either their fixed double shuttle box 73 or their replaceable box unit 75. If the shuttles are in the fixed double shuttle box 73 or 75

in the replaceable shuttle box unit 75, (Fig. 13) the levers 154 (Fig. 7), if they are in the fixed double shuttle box 73, or the levers 826 and 827 (Fig. 13) if they are in the replaceable box unit 75, are moved to elevate the daggers to safety position and permit them to pass over the bumpers 159.

Referring to Figs. 32 and 33, the rearwardly extending brackets 832 are connected at 833 to the element 834 of the magazine structure. Pivotally carried at 835, are the bell crank levers 836 having the vertical arms 837, and the horizontal arms 838. The lower ends of the vertical arms 837 are provided with the forwardly projecting lips 839.

The lever 838 of the bell crank lever 836 is connected to the rod 841. The lower end of the rod 841 has the pin 842 which is held in the slot 843 in the bell crank lever 844, the hub 845 of which lever 844 is pivotally connected to the pin 846 supported in the bracket 847.

The bell crank lever 844 has a downwardly projecting arm 848 which has a foot portion 849 resting in the recess 850 of the lever member 851. The lever 844 is normally retained by the spring 855 so that its horizontal arm will be held downward while the foot 849 will be held in engagement with the recess 850.

The lever member 851 is pivotally supported on the boss 953 of the frame member or bracket 847 and is provided with a depending collar member 853 which receives the slide rod 854. The resilient member or spring 856 holds the recess 850 of the lever 851 in close contact with the foot 849.

The rod 854 is provided with a collar 857. The resilient member 858 reacts between the collar 857 and the collar 853 of the lever 851.

As indicated in Fig. 32, the upper and lower dagger shafts 142 and 157 respectively, move forwardly and backwardly with the lay. The dagger 156 on the left side of the loom during normal operation will pass over the top of the bumper 159 which is connected to the operating mechanism of the loom (see elements 156a to 156d of Fig. 14).

In the embodiment of the present invention as shown in Figs. 32 and 33, the hub 859 on the dagger rod 157 is provided with a downwardly depending arm 860. This arm 860 has an inwardly projecting finger member 861 which normally rides below the heel 862 at the forward end of the rod 854. The hook 862 is maintained elevated above the finger 861 by engagement of the foot 849 of the lever 844 with the recess 850 of the lever 851, which remains in engagement as long as contact finger 839 can pass above the uppermost new reserve box unit 75², as indicated at 840 in Fig. 32.

Assuming that the box unit changing operation has just taken place and the shuttle box unit 75¹ has become the operating box unit, the magazine box unit 75² will have dropped into the elevator frame 79 to become the new reserve box unit 75².

If, however, the new reserve box unit 75² is canted or does not move properly into position, the finger 839 will be pressed backwardly upon the rearward movement of the lay by the box unit 75², raising the rod 841 and elevating the lever 844 to the dotted line position shown in Fig. 32. This will release the lever 851 and the spring 856, and will draw the horizontal arm of the lever upwardly on the pivot 852, lowering the

rod 854 and the hook 862 so it now engages with the finger 861.

As the lay now moves forwardly, carrying the dagger 156 together with the finger 861, the rod 854 will be drawn forwardly, compressing the spring 858 and at the same time moving the depending portion 860 rearwardly in respect to the lay, and the dagger 156 downwardly; as a result the dagger in its depressed position at 864 will contact with the bumper 159 and throw the loom 10 operating mechanism out, stopping the loom (see Fig. 14).

When the safety mechanism of Figs. 32 and 33 is being operated, the shuttles 72 will be in the fixed double shuttle box 73 and will press 15 out the swells 153 to elevate the dagger 156 to safety position (see Fig. 7). It is therefore necessary to provide a lost motion connection enabling relative movement between the dagger shaft 157 and the dagger lever 155 to permit the 20 dagger 156 to be lowered into throw-out position, even though the shuttles 72 are in position in the double shuttle box 73, when the mechanism of Figs. 32 and 33 is operated by improper placement of the new reserve box unit 75² in the 25 elevator frame 79.

As shown in Fig. 7, the dagger lever 155 connected to the shaft 157 at its lower end is provided with the inturned portion 864 which is connected to a hub 865. The hub 865 is freely 30 turnable upon the dagger shaft 157. The arm 866 is also provided with a hub (not shown) which is rigidly connected to the dagger shaft 157. The upper end of the arm 866 is provided with a pivotal connection 867 to a rod 868, which 35 passes through the dagger lever 155 and is provided near its rear end with an adjustable collar 869. The coil spring 870 is held between the dagger lever 155 and the collar 869.

When the dagger levers are moved rearwardly as shown in Fig. 7 by insertion of the shuttles 72 40 in the double shuttle box 73, the dagger lever 155 on the shaft 157 will press on the spring 870 and in turn upon the collar 869, moving the rod 868 rearwardly and through it the lever 866, whereby 45 the dagger 156 is elevated to safety position.

However, when the hook 862 and finger 861 in Figs. 32 and 33 are engaged, the dagger rod 157 will be turned to lower the dagger 156, turning the arm 866 of Fig. 7. As a result, the spring 870 will be compressed and the rod 868 will move 50 through the opening in the dagger lever 155. By this lost motion connection, it is therefore possible that the dagger 156 may be lowered to throw out the loom, even though the shuttles 72 55 are in position in the fixed double shuttle box 73.

It is to be understood that the details of construction of the various elements are merely illustrative and that they may be considerably modified in loom construction.

The shuttle box unit 75 of the present invention 60 may be readily modified to accommodate shuttles of different sizes and shapes than those specifically shown.

The elevator 77 may be driven by other arrangements than the cam 84 shown and described.

As shown, in the drawings, the pins 355 and 356 are employed to fix the position of the operating shuttle box unit 75, and the movement of 70 the elevator platform causes withdrawal of these pins to permit lowering of the operating box unit when exhausted. These pins, however, might be controlled by other means.

As shown, the box units 75, 75¹ and 75² and 75³ 75

move downwardly as also does the elevator 71 due to gravity. However, if desired, the elevator 71 and the box units 75 may be moved downwardly, as well as upwardly by other means.

5 As shown, the tracks 352 and 353 on the lowermost box unit 72 in the magazine frame 83 contact with the ends 583 and 583' (see Fig. 18) of the fingers 582 upon each forward movement of the lay. It may be desirable, however, to so support and control the box units in the magazine frame 83 and particularly the lower box unit 75² so that the contact between the tracks 252 and 253 and the fingers 582 and 582' would only take place when a transfer is being completed.

10 15 The box units in the magazine frame 83 may also be transferred to the elevator frame 79 by means other than the clips 545 and 545'.

20 In referring to the structure 79 as the elevator frame, the applicants are not excluding from the scope of the present application other constructions and modifications of the lay end which would permit achievement of the same result.

25 It is often desirable to align the lay and/or the elevator frame structure 79 with the magazine structure 83 and this may conveniently be accomplished by means of the arrangement shown diagrammatically in Fig. 14. In Fig. 14 it will be noted that the finger 945 projects forwardly from the upper portion of the elevator frame and is forwardly provided with a clevis into which extends the aligning member 946. The clevis on the finger 945 will move backwardly and forwardly upon the alignment element 946 so assurance will be had that the magazine frame 83 and the elevator frame 79 will also be in satisfactory alignment.

30 40 It is therefore apparent that the structure of the present invention enables the automatic removal of a box unit 75² from a stationary magazine 83, and then causes its advance to operating position. When the shuttles have become exhausted the box unit is removed without attention of the operator or stoppage of the loom. In addition to permitting of automatic replacement 45 of the shuttles when continuously using one type of filler, it is also possible to employ a standard type of multiple control or geared dial or cam, which will control repeat of electrical contacts and thereby produce a novel effect with various 50 types of fillers. In this latter case, for example, transfers might be made every fifty picks or multiples thereof to produce novel weaving effects.

55 The present invention is obviously applicable to a large variety of loom constructions, other than shown in Figs. 1 and 1a. Other methods of controlling the ground warp threads may be employed than shown in these figures.

60 If the main operating cam is modified to complete its operation over a longer period than four picks, a greater amount of reserve filling may be employed on the quills. It has been found most satisfactory to have the cam complete the transfer operation in four picks.

65 70 The chart of Fig. 38 shows the various timed relationships for a four picks cam. Indicated by the legends are the foremost and rearmost positions of the lay during the transfer and positions of the exhausted box unit and the reserve box unit, as well as the return of the elevator after removal of the exhausted box unit.

75 The transfer mechanism might also be actuated if desired manually even if the quills are not exhausted by providing a push button or other manually actuated device in the electrical circuit.

What is claimed is:

1. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and 10 said reserve shuttle box unit assembly into operating position when said replaceable operating shuttle box unit is exhausted, a frame structure at said other side of the lay to convey, guide and hold said reserve and replaceable unit assembly while in reserve position, while moving from reserve position to operating position and while moving out of operating position, and additional means to place the reserve shuttle box unit assemblies in the upper part of the frame and to 20 remove the exhausted shuttle box assemblies from the lower part of the frame, said unit assemblies and said frame structure being provided with cooperating groove and track guide means at the sides thereof to control the movement of 25 said unit assemblies, the shuttles being enclosed within said assemblies.

2. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle 30 box unit assembly out of operating position and said reserve shuttle box unit assembly into operating position when said replaceable operating shuttle box unit is exhausted, means to replace said reserve shuttle box unit assembly, a unit 35 frame structure at said other end of the lay to convey, guide and hold said replaceable and reserve unit assemblies in reserve position when moving from reserve position to operating position, and when moving out of operating position, 40 and electrical contact means associated with said fixed shuttle box assembly to cause operation of said shifting means when the replaceable shuttle box unit assembly is almost exhausted, said unit assemblies enclosing the shuttles and 45 extending beyond the ends of the shuttles and provided at the said extensions with sliding guides and said unit frame structure being provided with grooves cooperating with said sliding guides to control the movement of said unit assemblies. 50

3. In a loom construction, a fixed shuttle box assembly on one side of the lay, a replaceable operating shuttle box unit assembly on the other side of the lay, and a reserve shuttle box unit assembly adjacent said replaceable operating 60 shuttle box unit assembly to replace the same when exhausted, means associated with the fixed shuttle box assembly actuated when one of the shuttles therein has been exhausted, means at the replaceable operating shuttle box unit assembly 65 actuated by said first-mentioned means to move said replaceable operating shuttle box unit out of position and to move said reserve shuttle box unit assembly into operating position, a unit 70 frame structure at one end of the lay and movable with the lay to convey, guide and hold said reserve and replaceable shuttle box unit assemblies when moving from reserve position to operating position, when in operating position, and 75

- when moving out of operating position, and a magazine frame positioned above said unit frame structure, said magazine frame being fixed with respect to the loom, said magazine structure receiving additional reserve unit assemblies and being provided with means to transfer said unit assemblies successively into said unit frame structure.
4. In a loom construction, a fixed shuttle box assembly on one side of the lay and a replaceable operating shuttle box unit assembly on the other side of the lay, a reserve shuttle box unit assembly located above said replaceable operating shuttle box assembly to replace said replaceable operating shuttle box unit assembly when exhausted, a frame structure for holding said replaceable operating shuttle box unit assembly and said reserve shuttle box unit assembly, an elevator arrangement actuated upon exhaustion of the filler in the shuttle in the replaceable operating shuttle box unit assembly to lower the replaceable operating shuttle box unit out of position, thereby permitting the reserve shuttle box unit assembly to drop into position, and a unit frame structure fixed with respect to said lay at the other side of said lay to convey, guide and hold said reserve and replaceable unit assemblies when in reserve position, when moving from reserve position to operating position, when in operating position and when moving out of operating position and also to convey, guide and hold said elevator arrangement.
5. In a loom, a magazine structure carried on the loom frame containing a plurality of refilled shuttle box unit assemblies, a frame structure carried by the lay similarly carrying a pair of replaceable shuttle box unit assemblies, the lowermost of said shuttle box unit assemblies in said frame structure carried by the lay being in operating position, means actuated by the exhaustion of the filler thread in said last-mentioned shuttle box unit assembly to shift said operating shuttle box unit assembly out of position, permit the above shuttle box unit upon the frame to drop into operating position and to remove another shuttle box unit from the magazine onto the frame structure.
6. In a loom, a replaceable operating shuttle box unit assembly, a reserve shuttle box unit assembly located on the lay adjacent said replaceable operating shuttle box unit assembly and adapted to replace the same when exhausted, means actuated by the exhaustion of the filler thread in said replaceable operating shuttle box unit assembly to cause the said reserve shuttle box unit assembly to replace said replaceable operating shuttle box unit assembly, and means actuated by said last-mentioned means to cut the filler thread of said replaced operating shuttle box unit to separate it from the woven fabric, said means including a single cutter blade, holder means for said cutter blade, means to position said holder means so that the said blade will be substantially removed from the position of the fell, means to move said holder so that said blade will be at said fell upon replacement of the exhausted unit assembly, and means to actuate said holder so as to remove said cutter away from said fell position, after said filler thread has been severed.
7. In a loom, a fixed shuttle box unit assembly at one side of the lay, a replaceable operating shuttle box unit assembly at the other side of the lay, a reserve shuttle box unit assembly located on the lay adjacent said replaceable operating shuttle box unit assembly to replace the same when exhausted, means actuated by the exhaustion of the filler thread in said replaceable operating shuttle box unit to shift said replaceable operating shuttle box unit out of operating position and to shift said reserve shuttle box unit into operating position, a magazine fixed relatively and carried by the loom positioned above said reserve shuttle box in reserve position on said lay, said magazine receiving a plurality of reserve shuttle box unit assemblies, means to cause an exchange to take place resulting in the movement of a unit assembly from said magazine to said reserve position to replace the reserve shuttle box unit assembly when moved into operating position and a safety arrangement to stop the loom actuated if such exchange does not properly take place.
8. In a loom, a replaceable operating shuttle box unit assembly located in operating position, a reserve shuttle box unit assembly located adjacent said operating shuttle box unit assembly to replace the same when exhausted, a frame holding both shuttle box unit assemblies, a carrier means in said frame, means to actuate said carrier means when said replaceable operating shuttle box unit assembly has become exhausted, said carrier means serving to remove the replaceable operating shuttle box unit from operating position and to permit the reserve shuttle box unit to move into operating position, said actuating means including a cam and lever arrangement driven by the loom operating mechanism and also a latching mechanism so that the changing operation will take place between the time when the shuttles are received in the replaceable operating shuttle box unit and before the next throw of the picker stick, so that upon said throw the shuttles will be thrown from the newly replenished shuttle box unit.
9. In an automatic loom, a replaceable shuttle box unit construction consisting of a body member provided with a recess to receive a shuttle, a vertical track at one corner thereof and another vertical track at the diagonally opposite corner thereof to guide said box unit in a frame structure, and a vertical extension member at still another corner of the box unit, said tracks guiding the movement of said box unit while operating and said extension member with the track at the other side of the unit construction serving to position the unit construction while operating.
10. In a loom, a replaceable operating shuttle box unit, a reserve shuttle box unit for replacing said replaceable operating box unit when the filler therein is exhausted, an elevator frame receiving said replaceable operating box unit, and said reserve box unit, said elevator frame having vertical tracks cooperating with the correspondingly shaped tracks upon said box units, an elevator below the replaceable operating box unit, said elevator frame being provided with holding pins to hold said operating box in position, and means actuated by exhaustion of the filler in said replaceable operating box unit to lower said elevator and thereby release said pins, permitting said exhauster shuttle box unit to be removed by said elevator.
11. In a loom, a replaceable operating shuttle box unit assembly, a reserve shuttle box unit assembly, an elevator frame for receiving said assemblies, said elevator frame and said assemblies being provided with cooperating tracks, said elevator frame being provided with an elevator positioned below said operating box unit, said frame being provided with holding pins, whereby said operating box unit is held in position in said frame, and said box unit being also held in position.

- tion by pickers receiving the spurs of the shuttles when the shuttles are in position, means actuated upon exhaustion of said shuttle in said operating box unit to lower said elevator, and means actuated by the lowering of said elevator to move said pins thereby releasing said operating box unit, and to release the pickers from the shuttles.
12. In a loom, a plurality of groups of replaceable shuttle box units arranged one above the other with the lowermost shuttle box unit being the operating shuttle box unit, a frame upon the lay carrying the lower pair or group of said shuttle box units including the operating box unit and a frame upon the loom structure carrying the upper group of said shuttle box units, means actuated when the filler thread in the replaceable operating shuttle box unit is exhausted to lower said shuttle box unit out of position, said last mentioned means including an elevator arrangement, and means simultaneously actuated to transfer a box unit from said magazine frame to said lay frame actuated by said elevator when the lay is near its most forward position.
13. In an automatic loom construction, an elevator frame attached to the lay of the loom and moving therewith, said elevator frame receiving the operating shuttle box unit and a reserve shuttle box unit, said box units and said frame being provided with cooperating substantially vertical track members whereby said operating box units may slide downwardly out of operating position and said reserve box unit may slide into operating position, an elevator positioned below the operating box unit, a pair of holding pins positioned one in one track and one near the other track to hold the operating box unit in predetermined position in the frame, a lever arrangement to withdraw said pins and permit said operating box unit to drop when exhausted, said lever arrangement being actuated by the descent of said elevator to withdraw said pins from said tracks, and means actuated to lower said elevator when a shuttle in said operating box unit is exhausted.
14. In an automatic loom construction, a frame of U-shape with side members and a bottom member connected to and adapted to move with the lay, a magazine above said lay supported on the structure of the loom, said frame on said lay receiving an operating shuttle box unit, and a plurality of reserve shuttle box units, each box unit containing a pair of shuttles, means actuated when one of said shuttles in the operating box unit has been exhausted to remove the operating box unit from operating position whereby a reserve box unit in said elevator frame may slide into operating position, and means simultaneously operated to remove a box unit from the magazine and receive it in the elevator frame when the lay is near its extreme forward position.
15. In an automatic loom, an operating shuttle box unit and a reserve shuttle box unit, a frame member connected to the side of the lay and adapted to move with the lay, said operating shuttle box unit and said reserve shuttle box unit being received in said frame, and said frame and said box units being provided with cooperating tracks, an elevator mechanism contained in said frame below said operating box unit, means to lower said elevator when one of the shuttles in said box unit has been exhausted, lever means actuated by the said elevator to release the operating box unit, and additional lever means actuated by said elevator to cut the filling threads of said exhausted box unit.
16. In an automatic loom, an operating maga-
- zine frame containing an operating shuttle box unit, and a reserve shuttle box unit moving with the lay, a reserve magazine frame containing a plurality of additional shuttle box units fixed in respect to the loom, said frames being each provided with gravity track means, which coincide when the lay is near its extreme forward position, and means actuated when the lay is in such position and when the operating box unit is exhausted to cause a shuttle box unit to be transferred from said reserve frame to said operating frame.
17. In an automatic loom, a replaceable shuttle box unit construction consisting of a body member having two corners at each side and provided with a recess to receive the shuttle, a vertical track at one corner at one side thereof and another vertical track at a corner at the other side thereof to guide said box unit in a frame structure, and a vertical extension member at the other corner at said other side of the box unit, said members guiding said box unit enabling it to be correctly positioned during operating and enabling it to be ejected upon exhaustion, means for ejecting said exhausted box unit and hopper means receiving said exhausted box unit.
18. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, and frame structures positioned one above the other one carried by the loom and the other carried by the lay for receiving, guiding and holding said unit assemblies.
19. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, said lay also carrying a unit frame structure at said other side of the lay to convey, guide and hold said unit assembly, said unit frame structure being provided with means to hold said operating assembly in position, said reserve assembly resting upon the top of said operating assembly.
20. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, and said loom and said lay being provided with unit frame structures, at said other side to convey, guide and hold said unit frame assemblies, the loom unit frame structure being above the lay structure carrying a

5 plurality of additional unit assemblies and being provided with means to transfer said assemblies one at a time to said lay structure, each of said structures being provided with means to fix the position of the lowermost unit assembly, the other unit assemblies resting upon the fixed unit assemblies.

10 21. In a loom construction, a fixed shuttle box assembly on one side of the lay and a replaceable operating shuttle box unit assembly on the other side of the lay, a reserve shuttle box unit assembly located above said replaceable operating shuttle box assembly to replace said replaceable operating shuttle box unit assembly when exhausted, a frame structure for holding said replaceable operating shuttle box unit assembly and said reserve shuttle box unit assembly, a unit frame structure at said end of said lay to convey, guide and hold said unit assembly, means associated with said frame structure to lock said operating assembly in operating position, and means also guided and held in said structure for releasing said locking means to permit the exhausted assembly to drop out of position, said means then returning to hold the reserve assembly in said operating position.

15 22. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, a unit frame structure at said other end of said lay to convey, guide and hold said unit assembly, pin means associated with said frame structure to lock said operating assembly in operating position, and an elevator also guided and held in said structure for releasing said pin means to permit the exhausted assembly to drop out of position, said pin means then returning after lowering of the elevator and the exhausted unit assembly to hold the reserve assembly in said operating position.

20 23. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, a unit frame structure at said other side of the lay to convey, guide and hold said unit assemblies, sliding means received in said frame structure, said frame structure being provided with tracks to lock the transverse position of said unit assemblies and with pins to lock the vertical position of said unit assemblies, the operating assembly resting upon said pins and the reserve assembly resting upon said operating assembly and an elevator carried by said unit frame structure provided with means to release said pins upon being lowered and to permit return of said pins after removal of the exhausted unit assembly out of operating position, said pins

upon return holding said reserve assembly in position.

24. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, means to receive the exhausted unit assemblies located substantially below said operating position, and elevator means receiving said exhausted unit assembly and lowering it to said receiving means.

25 25. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, a unit frame structure at said other side of the lay to convey, guide and hold said unit assemblies, a receiving means to receive said exhausted assemblies positioned below said frame structure, and means carried by said frame structure to lower said exhausted unit assemblies from operating position to said receiving means.

30 26. A loom construction including a fixed shuttle box assembly located at one side of the lay, a replaceable operating shuttle box unit assembly located at the other side of the lay, and a reserve shuttle box unit assembly located on the lay adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, unit frame structures at said other side of the loom and other side of the lay, said loom unit frame structure being positioned above said lay in the frame structure and carrying a plurality of additional reserve unit assemblies, means in each of said unit frame structures to lock the lowermost assembly therein, and means carried by the lay unit frame structure to release said lowermost assembly from said locking means whereby the lowermost assembly in the loom structure may be lowered into the lay structure and the lowermost assembly in the lay structure may be lowered out of operating position.

35 27. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly

into operating position when said replaceable operating shuttle box unit is exhausted, said lay at said other side carrying a unit frame structure to convey, guide and hold said unit assemblies, 5 and said loom carrying a structure at said other side above said lay structure to receive additional reserve unit assemblies to be transferred one by one into said unit lay structure, and said loom also carrying a structure below said lay frame 10 structure to receive the exhausted assemblies after they have been moved out of operating position.

28. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, a unit 25 frame structure at the other side of the lay to convey, guide and hold said replaceable and reserve assemblies, receiver structures on said other side carried by the loom construction located above and below said lay unit frame structure, each of said loom receivers being adapted to receive a plurality of said assemblies, the upper receiver holding a plurality of additional reserve assemblies and the lower receiver holding a plurality of exhausted assemblies, and transfer means actuated after said exhaust assembly 30 has been lowered out of said operating position for transferring a reserve assembly from said upper loom receiver to said lay structure, and transferring said exhaust assembly from said lay structure to said lower loom receiver.

40 29. A loom construction including a fixed shuttle box assembly located at one side of the lay, a replaceable operating shuttle box unit assembly located at the other side of the lay, and a reserve shuttle box unit assembly located on the lay adjacent said replaceable operating shuttle box unit assembly to replace the same when exhausted, means to shift said replaceable operating shuttle box unit assembly out of operating position and 45 said reserve shuttle box unit assembly into operating position when said replaceable operating shuttle box unit is exhausted, a magazine structure located above the lay to replace said reserve assembly when said reserve assembly is shifted into operating position, and means to stop the operation of the loom in case said replacement does not take place properly.

30. A loom construction including a fixed shuttle box assembly located at one side of the lay, a 50 replaceable operating shuttle box unit assembly located at the other side of the lay, and a reserve shuttle box unit assembly located on the lay adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, a unit 55 frame structure at said other side of the lay to convey, guide and hold said operating and reserve shuttle box unit assemblies, a magazine frame located above said unit frame structure provided with a series of additional reserve shuttle box 70 unit assemblies, means to shift a reserve shuttle 75

box unit assembly from said magazine to said unit frame structure upon shifting of said first-mentioned reserve shuttle box unit assembly into operating position, said loom construction being of the type including a dagger safety mechanism, and means actuated to operate said dagger safety mechanism in case said transfer from the magazine to the unit frame structure does not properly take place. 5

31. A loom construction including a fixed shuttle box assembly using shuttles located at one side of the lay, a replaceable operating shuttle box unit assembly using shuttles located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, said loom construction being of the type having pickers with sockets in which the ends of the shuttles in said assemblies are received, picker sticks actuating said pickers and spring means to bias said picker sticks in one direction, and means actuated upon operation of said shifting means to release the shuttles in the operating shuttle box from said sockets of said pickers, said last-mentioned means including a rotary cam means 30 against which the picker stick is pressed by said spring, and means to rotate said cam means to permit additional movement of the picker stick under action of said spring means upon said operation of said shifting means. 35

32. In a loom, a replaceable operating shuttle box unit assembly, a reserve shuttle box unit assembly located adjacent said replaceable operating shuttle box unit assembly and adapted to replace the same when exhausted, means actuated by the exhaustion of the filler thread in said replaceable operating shuttle box unit assembly to cause the said reserve shuttle box unit assembly to replace said replaceable operating shuttle box unit assembly, and means actuated by said last-mentioned means to cut the filler thread of said replaced operating shuttle box unit to separate it from the woven fabric, said last-mentioned means including a single cutting edge device disposed at an inclination to the fabric, means to move said cutter device up to fell position where it will contact the filler thread of the replaced unit and cause said thread to slide up along the cutting edge due to its inclination, and means to cause withdrawal of said cutter device after it has cut said filler thread. 45

33. In a loom, a replaceable operating shuttle box unit assembly, a reserve shuttle box unit assembly located adjacent said replaceable operating shuttle box unit assembly and adapted to replace the same when exhausted, means actuated by the exhaustion of the filler thread in said replaceable operating shuttle box unit assembly to cause the said reserve shuttle box unit assembly to replace said replaceable operating shuttle box 60 unit assembly, and means actuated by said last-mentioned means to cut the filler thread of said replaced operating shuttle box unit to separate it from the woven fabric, said cutting means including a cutter blade, means to propel said cutter blade against said filler thread, and means actuated by the movement of the lay to withdraw said cutter blade out of cutting position. 65

34. In a loom, a replaceable operating shuttle box unit assembly located in operating position, a 70

reserve shuttle box unit assembly located adjacent said operating shuttle box unit assembly to replace the same when exhausted, a frame holding both shuttle box unit assemblies, an elevator 5 in said frame, said elevator serving to shift said reserve shuttle box unit assemblies into operating position and to shift said operating shuttle box assemblies out of position, when said replaceable operating shuttle box unit assembly has become exhausted, said actuating means including 10 a cam and lever arrangement driven by the loom operating mechanism and also a latching mechanism so that the changing operation will take place between the time when the shuttles are received in the replaceable operating shuttle box unit and before the next throw of the picker stick, so that upon said throw the shuttles will be thrown from the newly supplied shuttle box unit, said cam driving said lever during the period of 15 four complete reciprocations of the lay to cause said shifting of said unit assemblies.

35. A loom construction including a fixed shuttle box assembly located at one side of the lay, a replaceable operating shuttle carrier located at 25 the other side of the lay and a reserve shuttle carrier located adjacent said replaceable shuttle carrier, to replace the same when exhausted, means to shift said replaceable shuttle carrier out of operating position and said reserve shuttle carrier 30 into operating position when said replaceable shuttle carrier is exhausted, said last mentioned means including a device for removing the exhausted shuttle carrier out of position, a double latch device including two latches, one on each 35 side of said carrier actuated to grip said exhausted carrier when the lay is in an extreme position, said double latch device removing the shuttle carrier from the lay; and a magazine for receiving said exhausted carrier into which said exhausted carrier 40 will fall by gravity.

36. A loom construction including a fixed shuttle box assembly located at one side of the lay, a replaceable operating shuttle carrier located at the other side of the lay and a reserve shuttle carrier located adjacent said replaceable shuttle carrier to replace the same when exhausted, means to shift said replaceable shuttle carrier out of operating position and said reserve shuttle carrier into operating position when said replaceable shuttle carrier is exhausted, said exhausted shuttle carriers being received in a double magazine, the upper magazine being adapted to catch the shuttle carriers when they drop by gravity from the lay structure and to guide them into the lower magazine and the lower magazine being adapted to store said carriers.

37. The construction of claim 36 in which the lower magazine is provided with a resiliently supported shelf, which shelf is lowered against its resilient support to increase the capacity of the resilient magazine.

38. The structure of claim 36 in which the upper magazine is provided with a sloping guide arrangement and spring closed door, to guide the shuttle carrier in its fall, said spring pressed door being opened by the weight of the shuttle carrier and permitting said shuttle carrier to fall into the lower magazine.

39. A loom construction including a fixed shuttle box assembly located at one side of the lay, a replaceable operating shuttle box unit assembly located at the other side of the lay, and a reserve shuttle box unit assembly located adjacent said replaceable operating shuttle box 70 unit assembly to replace the same when ex-

hausted, means to shift said replaceable operating shuttle box unit assembly out of operating position and said reserve shuttle box unit assembly into operating position when said replaceable operating shuttle box unit is exhausted, said lay also carrying a unit frame structure at said other side of the lay to convey, guide and hold said unit assembly, said unit frame structure being provided with means to hold said operating assembly in position, said frame structure being provided with a shelf capable of being lowered and raised and having lever means to release the means holding the replaceable unit when exhausted so that it may drop by gravity onto said shelf, said shelf being operated to lower the exhausted unit to discharge position and discharge means provided to discharge said exhausted unit from said shelf in said lowered position, said shifting means raising said shelf after said discharge to its normal operating position below said operating unit. 20

40. A loom construction including a fixed shuttle box assembly located at one side of the lay, a replaceable operating shuttle box unit assembly located at the other side of the lay, and a reserve shuttle box unit assembly located adjacent said replaceable operating shuttle box unit assembly to replace the same when exhausted, means to shift said replaceable operating shuttle box unit assembly out of operating position and said reserve shuttle box unit assembly into operating position when said replaceable operating shuttle box unit is exhausted, and frame structures positioned one above the other, one carried by the loom frame and the other carried by the lay for receiving, guiding and holding said unit assemblies, the adjacent elements of said frame structure being provided with means to transfer the unit assemblies from the upper frame structure to the lower frame structure, said means including tracks upon the adjacent ends of the frame structures in 40 which said unit assemblies are received and oscillating means on the adjacent portions of the upper and lower frame structures to grasp the unit assemblies in the track of the lower structure and release them from the track of the upper structure 45 incidental to operation of said shifting means.

41. In an automatic shuttle changing loom, shuttle carriers, shuttles positioned therein, upper and lower structures respectively upon the side of the loom frame and lay to receive, guide 50 and position said carriers when held in operating position and when held in reserve prior to being moved into operating position and when moved out of operating position upon exhaustion, shifting means to move the carriers through and 55 between said structures and actuated upon exhaustion of the operating shuttles to shift said exhausted shuttle carrier out of operating position and a reserve shuttle carrier into operating position, said upper and lower structures being provided with track means and said carriers being 60 provided with complementary track means, the track means on the upper and lower structures being in coincidence upon foremost movement of the lay, said shifting means causing the track 65 means of the upper structure to release the complementary track means on a reserve shuttle carrier and the track means on the lower structure to grasp the complementary track means incidental to said shifting. 70

42. In an automatic shuttle changing loom, shuttle carriers, shuttles positioned therein, upper and lower structures respectively upon the side of the loom frame and lay to receive, guide and position said carriers when held in operating 75

- position and when held in reserve prior to being moved into operating position and when moved out of operating position upon exhaustion, shifting means to move the carriers through and between said structures and actuated upon exhaustion of the operating shuttles to shift said exhausted shuttle carrier out of operating position and a reserve shuttle carrier into operating position, said upper and lower structures being provided with track means and said carriers being provided with complementary track means, the movement of said carriers through said upper and lower structures to and out of operating position being entirely and substantially vertically downward and resulting from the force of gravity, the lowermost carriers in said upper and lower structures being prevented from moving downwardly by holder means, said shifting means releasing said holder means incidental to said shifting.
43. In an automatic shuttle changing loom, shuttle carriers, shuttles positioned therein, upper and lower structures respectively upon the side of the loom frame and lay to receive, guide and position said carriers when held in operating position and when held in reserve prior to being moved into operating position and when moved out of operating position upon exhaustion, shifting means to move the carriers through and between said structures and actuated upon exhaustion of the operating shuttles to shift said exhausted shuttle carrier out of operating position and a reserve shuttle carrier into operating position, said upper and lower structures being provided with track means and said carriers being provided with complementary track means and guard means associated with the lower structure operative to stop the loom if the movement of the carriers between said structures has not been satisfactorily completed.
44. In an automatic shuttle changing loom, shuttle carriers, shuttles positioned therein, upper and lower structures respectively upon the side of the loom frame and lay to receive, guide and position said carriers when held in operating position and when held in reserve prior to being moved into operating position and when moved out of operating position upon exhaustion, shifting means to move the carriers through and between said structures and actuated upon exhaustion of the operating shuttles to shift said exhausted shuttle carrier out of operating position and a reserve shuttle carrier into operating position, the lowermost carrier in said upper structure being supported on a ledge and being held at its

sides by a resiliently closed jaw member, the upper portion of said lower structure being provided with movable jaw members actuated by said shifting means incidental to said shifting to cause said lay to move said lowermost carrier 5 rearwardly off said ledge and release the carrier from said resiliently closed jaw members.

45. In an automatic shuttle changing loom, shuttle carriers, shuttles positioned therein, upper and lower structures respectively upon the side of the loom frame and lay to receive, guide and position said carriers when held in operating position and when held in reserve prior to being moved into operating position and when moved out of operating position upon exhaustion, shifting means to move the carriers through and between said structures and actuated upon exhaustion of the operating shuttles to shift said exhausted shuttle carrier out of operating position and a reserve shuttle carrier into operating position, said shifting means being provided with a shelf to move said exhausted carrier in said lower structure, and latch elements relatively fixed in respect to said lay, said movement of the exhausted carrier bringing it to the position of said latch elements so that it will be grasped thereby when the lay is in its forward position and held thereby when the lay moves rearwardly, whereby the exhausted carrier is removed from said lower structure. 30

46. In an automatic shuttle changing loom, shuttle carriers, shuttles positioned therein, upper and lower structures respectively upon the side of the loom frame and lay to receive, guide and position said carriers when held in operating position and when held in reserve prior to being moved into operating position and when moved out of operating position upon exhaustion, shifting means to move the carriers through and between said structures and actuated upon exhaustion of the operating shuttles to shift said exhausted shuttle carrier out of operating position and a reserve shuttle carrier into operating position, said lower structure being provided with a moving actuator element, with holding means to hold the operating carrier, with grasping means to grasp a reserve shuttle carrier in the upper structure and with actuating connections to be actuated by said actuator to release the holding means and permit the operating carrier to move 40 out of position and to actuate the grasping means 45 to remove a reserve shuttle carrier from the upper structure. 50
